UNITED STATES PATENT OFFICE

2,317,971

DENTAL EQUIPMENT STAND

Robert C. Angell, Prince Bay, N. Y., assignor to
 The S. S. White Dental Manufacturing Company, a corporation of Pennsylvania

Application April 5, 1939, Serial No. 266,174

44 Claims. (Cl. 32—22)

My invention relates particularly to that class of dental equipment assemblages that are adapted to be located adjacent to a dental operating chair and arranged to support, within easy reach of the operator, various instruments, implements, appliances and devices employed in the practice of dentistry, and is especially directed to its simplified construction, easy accessibility of its enclosed mechanism, wide range of relative movement of the associated parts, and the consequent flexibility in the use of such instruments.

The principal objects of my invention are to provide an assemblage of dental equipment devices embodied in stand or pedestal that is compact, pleasing in appearance, convenient to operate, readily assembled and taken apart and that affords a maximum degree of utility in the practice of the dental profession.

Other objects of my invention are to provide an equipment assemblage comprising a standard or pedestal upon which various relatively adjustable equipment and dental devices may be conveniently moved into relatively different operative positions about the common axis of said standard or pedestal.

Further objects of my invention are to provide a dental equipment stand assemblage in which the frame of the supporting standard is composed of a plurality of frame sections relatively superposed one upon another and secured together to form a supporting skeleton standard structure upon which the various equipment devices may be adjustably supported, and in which a shell or casing is formed of a plurality of casing sections having means cooperative with complementary means on said frame sections to cause said casing sections, when forced into their relative normal positions to closely embrace and enclose the assembled skeleton frame to form a pedestal structure or standard.

Other objects of my invention are to provide a dental equipment stand having a dental engine mechanism including the swingable arm and supporting collar mounted thereon and arranged to be swung about the vertical axis of said stand, and having its operative parts connected to be driven by a motor having its axis of rotation normally common to the axis of said stand and engine mechanism.

Another feature of my invention resides in providing a support for the motor, comprising a swingable cradle whereby said motor may be readily disconnected from the engine mechanism and swung horizontally clear of the supporting

standard and into position convenient for inspection and adjustment or repair.

My invention also includes a dental equipment stand or pedestal having a cuspidor mounted to swing horizontally about the axis of said pedestal and having its waste water outlet connected by a swivel joint with a waste water pipe disposed in coaxial relation with the stand or pedestal, and having a water niche in the wall of said pedestal providing convenient space for a drinking glass or tumbler and a superposed faucet for directing water into said tumbler, both being disposed in an alcove within the circumferential outer surface of the pedestal shell sections or casing and protected by the walls of said niche from any stray splashes that may be accidentally deflected from the spittoon bowl.

My invention further includes an equipment stand assemblage having a bracket table rotatably supported on a swingable supporting arm which is mounted for horizontal movement about the axis of said stand and including a frame carrying connection terminals for gas and air which are connected by flexible tubing spirally coiled about the common axis of said swingable supporting arm and stand with suitably disposed stationary connecting terminals of gas and air conveying pipes extending upwardly through the stand or pedestal.

Another object of my invention is to provide a spray bottle warming unit and X-ray illuminator swiveling mounted at the outer end of a swingable supporting arm which is in turn pivotally mounted on the bracket table arm and arranged to swing about the axis of the bracket table, whereby said spray bottle warming unit and X-ray illuminator are adjustable horizontally about three relatively spaced parallel axes.

My invention also includes brake and release mechanism incorporated in the bracket table arm whereby the table is held stable against possible accidental movement yet automatically released by pressure exerted by the operator to effect movement into the various desired positions in either direction from any possible stabilized position of rest.

An important object of my invention is to provide a dental equipment stand with a casing composed of a plurality of suitably shaped flexible closure sections preferably formed of stampings of sheet material and having means to engage with members of the frame of the stand and to be so engaged therewith and yieldingly restrained from relative separation within pre-determined limits that in event of accidental

leakage of gas and its ignition within said casing closure the consequent expansion of the contained mixture will not effect dismemberment of the composite envelope, but said closure sections will so yield to such limited extent as to permit the contained expanded mixture to escape through the interstices provided by the limited yielding of said flexible casing sections.

My invention contemplates a dental equipment stand having a spotlight carried by a swingable arm which is mounted for horizontal oscillation about the vertical axis of said stand and may preferably have its supporting collar disposed at the top of said stand and directly subjacent to the supporting collar of the dental engine mechanism.

My invention also embraces the electrical connection of relatively movable terminals and includes novel means for so guiding the interposed current conveying cord in such predetermined condition as to prevent its accidental displacement or entanglement when one terminal is moved relative to the other.

Specifically stated, the form of my invention as hereinafter described, comprehends an equipment stand comprising a pedestal of generally cylindrical formation having a flanged base and a dome-like upper extremity from which projects a cylindriform engine mechanism mounting, and having horizontally swingable arms disposed at relatively different levels and respectively carrying a bracket table and a cuspidor. Said pedestal is preferably formed of a plurality of separable frame sections each designed to provide specifically for its intended purpose and assembled one upon another in a prescribed order and secured together with their respective axes coincident with the axis of the thus assembled standard which provides a supporting frame standard that may be enclosed by a plurality of readily removable and replaceable substantially semicylindrical casing sections preferably of sheet material assembled to form the cylindriform pedestal structure. The swingable arms for the bracket table and cuspidor are provided with suitably formed casing sections of sheet material which have their inner semicylindrical ends in coincident alinement with the cylindrical wall formed by the adjacent casing sections and serve to form therewith the complete shell or closure for the above described assembled supporting standard, and providing the cylindriform pedestal structure as illustrated.

My invention also includes all of the various novel features of construction and arrangement as hereinafter more definitely specified.

In the accompanying drawings, Figure 1 is a plan view of the equipment stand assemblage showing the foot controller and its relation to the operating chair; Fig. 2 is a front elevational view of the equipment stand shown in Fig. 1; Fig. 3 is a front elevational view of said equipment stand with the front casing members removed and showing the bracket table arm and spittoon arm in section; Fig. 4 is a rear elevational view of certain of the intermediate frame sections assembled and including the main body frame section, the spittoon arm frame section and the water niche frame section; Fig. 5 is a fragmentary front elevational view of the base frame section and a fragment of the lower portion of the main frame section and showing the inlet and waste pipes extended therethrough with certain portions thereof indicated in section; Fig. 6 is a plan sectional view of the structure

assemblage shown in Fig. 5 as indicated on the line 6—6 in said figure, the casing sections shown in Fig. 5 being omitted from Fig. 6 for convenience of illustration; Fig. 7 is a central vertical sectional view of the main body frame section 5 therethrough and including the water inlet valve and condensate relief valve; Fig. 8 is a central vertical sectional view showing upper and lower 10 fragments of the main body frame section and the superposed cuspidor frame section and water niche frame section; Fig. 9 is a central vertical sectional view of the upper portion of the equipment stand and including a fragment of the water niche frame section, the superposed table bracket arm frame section and motor frame section with its engine supporting head; Fig. 10 is a side elevational view of the cuspidor arm together with fragments of the pedestal associated therewith, and showing mounted thereon the warm water syringe with its flexible connector, the saliva ejector with its flexible connector, and the flush mechanism with its nozzle; Fig. 11 is a plan view of the cuspidor arm and its mounting 15 the cuspidor arm frame section, said mounting and the casing for the cuspidor arm being shown in section for convenience of illustration; Fig. 12 is a side elevational view of the cuspidor arm with the cuspidor mounted thereon, together with a fragment of the cuspidor mounting frame 20 which is shown partly in section for convenience of illustration; Fig. 13 is a vertical longitudinal sectional view taken axially through the cuspidor mounting frame and the cuspidor arm and bowl mounted thereon; Fig. 14 is a plan sectional view taken through the water niche section on the line 14—14 in Fig. 8, and showing a fragment of the cuspidor drain conduit; Fig. 15 is a plan sectional view taken on the line 15—15 in Fig. 13, 25 the cuspidor drain conduit and certain associated parts being shown in plan view for convenience of illustration; Fig. 16 is a plan view of the table bracket arm and its support, certain of the parts including the casing being shown in section for convenience of illustration; Fig. 17 is a fragmentary plan view of the inner end portion of the bracket table arm and its mounting frame section and showing the air and gas connections extending into the bracket table arm from the supply pipes leading through the pedestal structure, 30 portions of the bracket table arm casing being shown in section for convenience of illustration; Fig. 18 is a fragmentary central vertical sectional view taken on the line 18—18 in Fig. 17; Fig. 19 is an enlarged plan sectional view taken on the line 19—19 in Fig. 18 through the air and gas supply connection block; Fig. 20 is a front elevational view of the air and gas connecting block shown in Figs. 17, 18 and 19; Fig. 21 is a plan sectional view taken through the motor frame section on the line 21—21 in Fig. 9 and showing in plan view the air and gas controlling mechanism, the motor being shown swung outwardly on its carriage into convenient position for inspection or repair; Fig. 22 is an enlarged vertical sectional view of the gas controlling valve shown in Fig. 21 together with fragments shown in section of the mounting for said valve and the motor casing section; Fig. 23 is an enlarged inverted plan sectional view of the air control valve shown in Fig. 21; Fig. 24 is a front elevational view of the mounting for the air and gas controlling valves and the switches for controlling the various electrical devices employed, said mounting being developed in a plane together with the parts 35 40 45 50 55 60 65 70 75

mounted thereon and the casing section being shown in dot-and-dash lines for convenience of illustration; Fig. 25 is a fragmentary vertical sectional view taken centrally and transversely through the mounting shown in Fig. 24 on the line 25—25 in said figure; Fig. 26 is a fragmentary vertical sectional view taken centrally and transversely through the mounting on the line 26—26 in Fig. 24; Fig. 27 is a horizontal sectional view of the main body section taken through the main water control valve on the line 27—27 in Figs. 7 and 8; Fig. 28 is a fragmentary horizontal sectional view taken through the condensate relief valve on the line 28—28 in Fig. 7; Fig. 29 is a central longitudinal vertical sectional view of the warm water syringe holder which is shown mounted on the cuspidor arm in Fig. 10, the upper portion being shown in elevation for convenience of illustration. Fig. 30 is a transverse vertical fragmentary sectional view taken through the cuspidor arm on the axial plane of the warm water syringe holder and showing its means of attachment, the plane of said section being normal to the plane of the section shown in Fig. 29 and taken on the line 30—30 in Fig. 10; Fig. 31 is an enlarged front elevational view of the accessory bracket table arm lock and release mechanism shown in Fig. 16, including a fragment of the brake ring; Fig. 32 is an enlarged plan sectional view of the lock and release mechanism shown in Fig. 31 taken on the line 32—32 in Figures 31 and 33 and including a fragment of the brake ring; Fig. 33 is an enlarged transverse vertical sectional view of the lock and release mechanism shown in Figs. 31 and 32 taken on the line 33—33 in Fig. 32; Fig. 34 is a perspective view of the ball retaining plate shown in Figs. 32 and 33 but removed from Fig. 31; Fig. 35 is an enlarged vertical transverse sectional view of the accessory bracket table arm brake and its cooperative brake ring shown in Fig. 16, taken on the line 35—35 in said figure; Fig. 36 is a perspective view of one of the similar opposed clamp blocks which retain the opposed friction brake pads, as best shown in Fig. 35; Fig. 37 is a full sized front elevational view of the electrical controlling switch shown in the bracket table arm illustrated in Fig. 16; Fig. 38 is a central vertical sectional view of a simplified form of bracket table shown mounted upon the outer end of the bracket table arm; Fig. 39 is a fragmentary perspective view of the main frame section cover or casing and typifies the covers or casings of the other frame sections which serve to form the stand or pedestal; Fig. 40 is a fragmentary plan sectional view taken in a horizontal plane through the reduced upper semicircular end region of the cover or casing section shown in Figs. 8 and 39, and through the ring or band illustrated in Fig. 8, and showing the means of securing the overlapping ends of said ring or band to said casing section; Fig. 41 is a perspective view of the band or ring shown in Fig. 40 and of which there are several employed to girdle the pedestal at variably spaced regions of junction between the several casing sections; Fig. 42 is a plan view of the pedestal with the bracket table arm carrying the bracket table and embodying a secondary or forearm swingable horizontally about the axis of the bracket table and carrying at its free end a spray bottle heater and X-ray illuminator rotatably mounted thereon; Fig. 43 is a front elevational view of the structure shown in Fig. 42, exclusive of the pedestal, certain parts being shown in section for convenience of illus-

tration; Fig. 44 is a front elevational view of the spray bottle heater and X-ray illuminator with a fragment of the swingable arm upon which they are mounted, a portion of the forward wall of said illuminator being broken away to better illustrate the interior parts; Fig. 45 is a transverse central vertical sectional view of the spray bottle heater and X-ray illuminator assembly, the upper portion of said spray bottle heater being shown in elevation for simplification; Fig. 46 is a fragmentary plan sectional view of the assembled structure shown in Fig. 45 taken on the line 46—46 in Fig. 45, and showing a fragment of the spray bottle heater frame; Fig. 47 is a side elevational view of the spray bottle, of which there are two shown in Fig. 44; Fig. 48 is a vertical longitudinal sectional view of the spray bottle heater shown in Figs. 42, 43 and 44 taken axially through the spray bottle receptacles; Fig. 49 is a plan view of the supporting frame of the spray bottle heater, shown mounted for rotation upon a fragment of the outer end of the secondary or forearm of the bracket table arm; Fig. 50 is a horizontal sectional view of the spray bottle heater taken on the line 50—50 in Fig. 48; Fig. 51 is a transverse vertical sectional view taken axially through the water glass receptacle, the X-ray illuminator attached thereto being shown in end elevation; Fig. 52 is a horizontal sectional view of the secondary or forearm which supports the spray bottle heater and illustrates the means for preventing entanglement of the electric cords leading therethrough to said spray bottle heater and X-ray illuminator when said arm is swung upon its axis of rotation; Fig. 53 is a fragmentary vertical sectional view taken through the electric cord directing guide on the line 53—53 in Fig. 52, a portion being shown in elevation for convenience of illustration; Fig. 54 is a perspective view of the electric cord directing guide which is shown in plan view in Fig. 52; Fig. 55 is a perspective view of the electric cord supporting guide to which said electric cord is attached and guided thereby into the spray bottle heater; Fig. 56 is a perspective view of the clip by which said electric cord is attached to said supporting guide; Fig. 57 is a side elevational view of the spotlight with its articulated arm mounted upon the top of the equipment stand pedestal for rotation about the axis of said pedestal; and Fig. 58 is a wiring diagram showing the connections between the instrument transformer, the booster transformer and the controlling switches.

In said figures the frame forming the supporting standard comprises the base section 1, the main body section 2, the combined water niche and cuspidor section 3, accessory table-arm section 4 and the dome or motor section 5, all being assembled by building one upon the other about a unitary common vertical axis in the order named to provide a skeleton standard structure upon which the various operating appliances, devices and parts, to be hereinafter described, may be mounted for convenient utilization.

The base section 1 is provided with the enlarged base flange 6 adapted to rest upon the floor and to be secured thereto by the bolts 7 extended through suitably spaced apertures 8, and has four upwardly extending legs 9, terminating in a substantially octagonal perforated elevated plate or platform 10, having the circular apertures 11, 12, 13 and 14, and the elongated aperture 15, through which piping and electrical conduits may extend, said platform 10 being pro-

vided with two diametrically opposite outwardly projecting lugs 16 each having a vertical notch or slot 17 cut or otherwise formed therein, and indented for a purpose to be hereinafter described.

Superposed upon the base section 1 is the main body section 2 which comprises the relatively spaced parallel plane side walls 19 and 20 respectively terminating at their lower ends in the annular horizontally extended flange 21 and at their upper ends in the annular horizontally extended flange 22, and being joined vertically by the transverse wall 23 which is inset from the edges of said walls 19 and 20 but preferably disposed nearer to the rear edges of said walls, as shown in Figs. 6 and 8.

The transverse wall 23 terminates short of the annular flange 21 and merges into the horizontally extended shelf 25 projecting rearwardly from the lower end of said transverse wall 23 and having its curved free edge 26 joining the free vertically disposed rear edges of the side walls 19 and 20, as shown in Figs. 3, 4 and 6.

Said transverse wall 23 is slightly offset at 27, its upper portion, see Fig. 8, and merges horizontally into the flange 22, the horizontal portion being provided with the aperture 28 for the convenient passage of an electrical conduit 29 therethrough, as shown in Figs. 4 and 8. Said flange, as shown in Figs. 7 and 8, is provided at its inner edge with the upwardly extending rectangular rim bead 30.

The main body section 2 is supported on the base section 1 and has the four feet 31 which depend from the under surface of the annular flange 21 in relatively spaced relation and rest upon the plate or platform 10 of base section 1 to which the main body section 2 is rigidly secured by the bolts 32, shown in Fig. 3.

The flanges 21 and 22 of the main body section 2 are provided in their outer peripheral edge with the diametrically opposite vertically disposed slots or notches 35 and 36 respectively which afford attachment of the casing members, as will be hereinafter described.

The combined niche and cupid mounting section 3 is superposed upon the main body section 2 and comprises a unitary structure having the cylindriform wall 37 provided with a lower annular horizontal flange 38 resting upon the upper flange 22 of said main body section 2, a medial flange 39 from which rise the four posts or standards 40 terminating upwardly in the top plate or cap 41 unitary therewith and having a central aperture 42 and flange 43, and providing a circular horizontal track 44 and a cylindrical vertical track 45 for supporting bearing structure to be later described.

The cylindriform wall 37 of the water niche and cupid mounting section 3 is provided with the apertures 46 and 47 and has the annular rectangular bearing rib 49 in the form of an outwardly projecting encircling band interposed between the flanges 38 and 39, but more closely adjacent to the latter.

As best illustrated in Fig. 8, the annular flange 38 is provided with the rabbet 50 arranged to receive the rim bead 30 on the flange 22 of the main body section 2, and said flange 38 is rigidly secured to said flange 22 by the bolts 51, as shown in Fig. 3. The flanges 39 and 43 are each provided in their peripheral edges with diametrically opposite notches or slots 52 and 53 respectively, see Figs. 9 and 14, the purpose of which will be later referred to.

The accessory table-arm section 4 is superposed upon the water niche and cupid mounting section 3, and, as best shown in Fig. 9, comprises a hollow circular hub 54 having a depending inner rim bead 55 extending into a correspondingly formed recess or rabbet 56 in the cap 41 of the water niche and cupid mounting section 3 to which said section 4 is secured by bolts 57, one of which is shown in the plane of section 10 in Fig. 9. Said accessory table-arm section 4 is provided with the horizontal flange 58 disposed intermediate of its axial length and having a depending annular projection 59 providing a flat horizontal under surface affording a circular 15 roller bearing track 60 in suitably opposed spaced relation to the circular track 44 on the cap 41. The upwardly extending portion of said hub 54 is externally recessed to provide the shoulder 61 arranged to support the annular shelf 62, and 20 terminates upwardly in the inner rim bead 63.

The motor section 5 is superposed upon the accessory table-arm section 4 and serves as a crown-piece or dome for the skeleton standard structure thus assembled. Said motor section 5 25 comprises the annular floor 65 having the lower edge of its inner rim rabbeted to receive the upwardly extending inner rim projection or bead 63 on the circular hub 54, and to be secured thereto by the bolts 66, shown in Fig. 3, and from 30 which floor 65 rise the diametrically opposite U-shaped standards 67 respectively curving inwardly at their upper extremities and merging into the annular head 69 forming a pocket 70 arranged to receive specially designed dental engine mounting structure.

The engine arm mounting structure includes the engine arm support comprising the cylindriform hub 71 disposed coaxially with the axis of the assembled standard structure, and having the 35 horizontally disposed flange 72 engaged in the pocket 70 in rigid relation to the motor section 5 by the bolts 73, as best illustrated in Fig. 9.

The hub 71 of the engine arm support is normally encircled by the spacer sleeve 74, above 40 which the engine arm bearing 75 having the radially extending horizontal bearing flange 76 is disposed in threaded engagement with the upper extremity of the hub 71, and rotatably adjusted thereon to firmly engage the limiting 45 shoulder 77 on said hub 71.

The engine arm bearing 75 supports for rotatable movement, the inwardly flanged swivel ring 79 of the engine arm base from which the engine arm supporting bracket 80 projects radially and 50 slightly upward, and said swivel ring 79 is retained in rotatable relation to the bearing 75 by the nut 81 in threaded engagement with the upper portion of said bearing 75, said nut being held in adjusted position by the set screw 82.

The swivel ring 79 and its engine arm supporting bracket 80 is adapted to carry the dental engine, of well known construction, and comprising the main engine arm 83, the intermediate arm 84 and the forward arm 85, the latter having 55 the attachment stem 86 to which a hand-piece of well known construction may be attached and driven by a cord belt of well known construction passing around the idler pulleys 89, 90, 91 and the driving pulley 92 in a well known manner.

The mode of actuating the dental engine and the driving pulley 92 differs widely from that heretofore employed in that the driving pulley 92 is carried by the driving pulley extension shaft 93 which is coaxial with the armature 95 of the 70 electric motor 96, and with the vertical axis of

the pedestal in the dome of which the electric motor is mounted.

The driving pulley shaft 93 is mounted for rotation in the relatively spaced bearing bushings 97 and 99 which are engaged in the bearing sleeve 100 having the horizontal flange 101 supported in threaded engagement with the upper end of the hub 71 of the engine arm support, said pulley shaft 93 being conveniently lubricated through the oil passageway 102 extending through the walls of said bearing sleeve 100 and uppermost bearing bushing 97.

The driving pulley shaft 93 is preferably connected with the motor armature shaft 103 by flexible connecting means that may not only provide for readily connecting and disconnecting said shafts but which also tend to prevent transmission of possible vibration incident to the actuation of the motor armature.

Said flexible connecting means include the thimble 105 secured to the lower extremity of said engine driving pulley shaft 93 in a predetermined relation by the set screw 106, the coupling collar 107 axially adjustable on the upper portion of the armature shaft 103 and having the key 109 extending into the longitudinal groove or spline 110, and having the opposed set screw 111 extending into the groove or spline 112 disposed in diametrically opposite relation to the groove or spline 110.

As best shown in Fig. 9, said thimble 105 and collar 107 are arranged to be connected, for concurrent rotation, by the flexible connector or coupling which may preferably comprise the central core 115 and the encircling metal rims 116 and 117 relatively spaced axially and connected with said central core 115 by the flanges 119 and 120 of rubber or other suitable material, the rim 116 being shown as permanently engaged with the thimble 105 and the rim 117 is permanently engaged in the coupling ring 118 which is removably connected with the collar 107 by the set screw 121.

Said set screw 121 is diametrically opposed to the key 122 in the collar 107 and said key 122 and set screw 121 respectively engage diametrically opposite parallel slots or splines 123 and 124 extending longitudinally in the cylindrical surface of the ring 118.

From inspection of Fig. 9 and the above description it will be obvious that by loosening or backing out the set screws 111 and 121, the coupling collar 107 may be moved downwardly on the motor armature shaft 103 sufficiently to disengage said collar 107 from the connector ring 118 and to so free the motor 96 and its armature shaft 103 as to permit its free withdrawal laterally.

In order that the parts of the motor 96 may be conveniently inspected, adjusted, repaired or replaced, as may be found necessary or desirable, it may preferably be mounted upon the laterally movable cradle 125 which is mounted to swing outwardly from the pedestal axis as shown in Fig. 21 on the pintals 126 and 127 which, as shown in Fig. 9, are engaged in suitably provided apertures 129 and 130 in the hinge lugs 131 and 132 projecting inwardly from one of the U-shaped standards 67, as shown at the right hand side of the motor frame section 5 as shown in said Figure 9.

The cradle 125 includes the motor supporting shelf 133 which is provided with the four relatively spaced attachment lugs 135 projecting upwardly and outwardly and each having an aper-

ture 136 therein provided with a shoulder 137 and in which are mounted vibration absorbing resilient supports 139 upon which the electric motor 96 may rest and be supported thereby free from audible vibration.

The resilient supports 139 each comprise an annular rim 140 preferably of a hard or stiff material such as metal, and embracing a circular body of rubber or other resilient material and 10 having an enlarged hub 142 through which the screws 143 extend in threaded engagement with the motor shell bosses 145.

As shown in Fig. 21, the cradle 125 carrying the motor 96 may be swung outward from its 15 normal operating position in which said motor is maintained in axial alinement with the driving pulley shaft 93, to a position substantially beyond the line of the pedestal body so that said motor may be readily inspected, adjusted, oiled, repaired or replaced.

As also shown in Figs. 9 and 21, the cradle 125 is provided with a stop lug 146 projecting from its motor supporting shelf 133 and arranged to engage the stop buffer 147 projecting from the left hand U-shaped standard 67 into the arcuate path of said stop lug 146 and thereby limit the swinging movement of the motor in such centered position that its axis is in operative coaxial alinement with the axis of the engine driving pulley shaft 93.

Said cradle with its motor 96 is arranged to be held in its operative position by the clamp set-screw 150 having the knurled head 151, in threaded engagement with the lug 152 on said cradle shelf 133, and so arranged that when said clamp set-screw is backed off, the free end of its knurled head 151 engages the vertically extending flange 153 of the left hand U-shaped standard 67, as indicated in Figs. 9 and 21, to tightly engage the stop lug 146 against the buffer 147.

As shown in Figs. 21, 24, 25 and 26, certain of the controlling devices are carried by the motor frame section 5 and comprise the main switch 155 having the control lever 156, the low voltage switch 157 having the control lever 158, the temperature control switch 159 having the control knob 160, the gas control valve 161 having the control knob 162, and the air control valve 163 having the control knob 164, and also includes the pilot lamp 165, all of which are mounted on the control panel 166 which is attached to said motor frame section 5 by the angle bracket 167 at its lower end and at its upper end by the angle bracket 169, as indicated in Figs. 24 and 25.

The accessory table arm 170, as best illustrated in Fig. 16, is adapted to oscillatably swing horizontally about the unitary axis of the standard structure upon which it is supported, and its frame 168 comprises substantially parallel side bars 171 and 172 merging outward at the free end of said arm into an annular mounting 173 upon which an accessory table such as shown in Figs. 1 and 2 may be conveniently supported. Said frame 168 is provided with the several outwardly projecting vertically disposed ribs 174.

The inner ends of the side bars 171 and 172 merge into a substantially semicircular bearing mounting 175, the rim of which embraces the hub 54 in concentric relation thereto, and the free end portions 176 and 177 thereof are connected by the yoke 179 which is secured thereto by the screws 180 and 181 and serves to provide a substantially annular inner terminal

structure encircling said hub 54. Said yoke 179 is provided with the outwardly projecting ribs 178 adjacent to its opposite ends.

As best illustrated in Fig. 16, the table arm 170 is supported for horizontal movement into different positions convenient to the operator, by the supporting rollers 185, 186, and 187 respectively mounted on the headed trunnions 188, 189 and 190, which project inwardly from the bearing mounting rim 175.

The rollers 185 and 186 serve best to directly carry the weight of the projecting arm 170 and the parts supported thereon and consequently are disposed relatively close to each other upon opposite sides of a vertical plane passing through the axes of the annular ends of the accessory supporting arm frame, and roll upon the track 44, see Fig. 18, while the roller 187 which serves to balance the arm 170 on said rollers 185 and 186 rolls upon the opposed superjacent track 60, shown in Figs. 9, 18 and 35, and is preferably disposed with its axis of rotation substantially coincident with said vertical plane.

As shown in Fig. 16, the trunnion 190 has the reduced relatively eccentric screw threaded shank 191 which, as best shown in Fig. 9, is engaged by the nut 192, adjustable to hold the encircling ball race annulus 193 in rigid engagement with the boss 194 projecting inwardly from the bearing mounting 175. Similarly, the trunnion 189 has the eccentric shank 195 engaged by the nut 196. It will be obvious from the foregoing description that by proper rotation of the shanks 191 and 195 of the respective trunnions 189 and 190 the bracket table arm 170 may be adjusted to a substantially level position.

As shown in section in Fig. 9, the roller 187, which is typical of the rollers 185 and 186, is annular in form and is provided with a ball race 197 in its inner cylindrical surface, in opposed relation to the ball race 198 in the outward surface of the ball race annulus 193, and relatively revolves about said annulus on the bearing balls 199 which are arranged to traverse the opposed ball races 197 and 198.

In order to retain the accessory table arm 170 in axial registry with the supporting standard structure or pedestal, it is provided with the horizontally disposed equally spaced rollers 200, 201 and 202 arranged to traverse the cylindrical track 45, the roller 200 being disposed between the rollers 185 and 186 with its axis of rotation in a vertical plane coincident with the axis of the supporting roller 187 and journalled to rotate on the headed shaft 203 which, as shown in Fig. 9, extends through an aperture in the boss 205 on the inwardly projecting rib 206 of the bearing mounting 175, and which is engaged in stationary relation therewith by the nut 207 threaded thereon.

Similarly, the roller 201 rotates upon the headed shaft 209 which extends through an aperture in the boss 210 on the inwardly projecting rib 211 and which is rigidly engaged therewith by the nut 212 threaded thereon. Likewise, the roller 202 is carried by the yoke 179 and rotates on the headed shaft 213 which extends through an aperture in the boss 214 on the rib 215 extending inwardly and adapted to brace said yoke, said headed shaft 213 being secured in rigid relation to said boss by the nut 216 threaded thereon.

Thus it will be seen that the accessory table arm 170 may freely revolve about the axis of

the standard structure and be moved into any desired position convenient to the operator. However, it has been found desirable to adjustably restrict its too free movement and to prevent its over running when its position is changed, and therefore a brake device is employed which, as shown in Figs. 16 and 35, comprises the annular disk 217 which is rotatably engaged between the water niche and cuspidor 10 mounting section 3 and the accessory table arm section 4, and which is frictionally engaged between the jaws 219 and 220 of the brake device comprising the opposed jaw plates 221 and 222 respectively having the opposed lips or ridges 223 and 224 upon which they may slightly rock.

Said jaw plates are respectively provided with pockets 225 and 226 in which friction pads 227 and 229 are held in opposed relation in frictional engagement with the upper and under surfaces 20 of said disk 217 respectively, said pads 227 and 229 being engaged with said disk in any desired degree of yielding frictional contact with said disk 217, see Fig. 35, by the adjusting screw 230 which extends through the aperture 231 in the jaw plate 222 and into threaded engagement with the jaw plate 221. Said adjusting screw 230 is encircled by the spiral spring 232 disposed between its head 233 and the jaw plate 222, and has the reduced end 235 extended into the aperture 236 in the accessory table arm section 4, whereby it is retained and prevented from radial displacement in the pocket 237 in the cap 41 of the water niche and cuspidor section 3.

The accessory table arm 170 is normally locked in engagement with said annular disk 217, so that it may be moved only by considerable manual pressure, the amount of which depending upon the frictional pressure of the friction pads 227 and 229 incident to the adjustment of said adjusting screw 230, but said arm may be automatically released from such locked engagement to freely move about its axis of rotation.

The mechanism for effecting such locking and automatic release of the accessory table arm 45 comprises a supporting plate 239 secured to the rib 211 by the bolts 238, and carrying the lock housing 240 mounted on the studs 241 and 242 projecting upwardly from said plate 239, and permitting a slight up and down movement thereon. Said lock housing 240 has the recess 243 into which the peripheral margin of the annular disk 217 extends in slidable engagement with the floor 245 of said recess. The lock housing 240 embraces the ball cage block 246 providing the ball pocket 247, the upper wall of which includes the oppositely inclined under surfaces 249 and 250 inwardly approaching in spaced relation the upper surface of the peripheral margin of the annular disk 217, and between said surfaces the locking balls 251 and 252 are retained in said pocket and yieldingly pressed toward each other into operative engagement with the said oppositely inclined surfaces by the springs 255 and 256 which are engaged in the thimbles 257 and 259 removably disposed in the recesses 260 and 261 in the outer end portions of the ball cage block 246 which is engaged in the housing 240 by the screws 262.

As shown in Figs. 31 and 32, the balls 251 and 252 are normally pressed toward each other by the springs 255 and 256 and into locking contact with the respective oppositely inclined under surfaces 249 and 250 and with the upper surface of the annular disk 217, and are retained in the ball pocket 247 by the ball retaining plate

or keeper 263, shown in Figs. 32, 33 and 34, by the screw 264 extended through the aperture 265 in said plate 263 and into the threaded aperture 266 in the housing 240.

The locking balls 251 and 252 are arranged to be separated to render them temporarily inoperative as a locking medium by the plunger bolt 269 having the tapered or conical forward end 270 disposed between said locking balls, see Fig. 32, and operative when moved forward to separate said balls and to thereby force them out of operative contact with the relatively inclined surfaces 249 and 250 thereby permitting free movement of the accessory table arm 170 about the axis of the supporting standards.

As shown in Figs. 32 and 33, the plunger bolt 269 is provided with the head 272 against which the spiral spring 273, disposed in the bore 275 in the lock housing 240 and encircling said bolt, bears to normally effect movement of the bolt 269 tending to withdraw its conical or tapered end 270 from between said locking balls 251 and 252, so that they may be caused by the springs 255 and 256 to approach each other to effect a locking action, as above described.

The forward movement of the bolt 269 effects unlocking of the device just described and is effected by means of the bell-crank-lever comprising the lever arm 276, the lever arm 277 and the connecting rod 279 which is journalled in the plate 239; the lever arm 276 engages the head 272 and is arranged to force the plunger bolt 269 forward when the lever arm 277 is rocked to the right as indicated by the arrow in Fig. 32.

As shown in Fig. 16, the bell-crank-lever arm 277 is connected by the connecting rod 279 through the yoke 280 with the double bell-crank-lever 281, said connecting rod 279 having its threaded terminal 282 extended through the upturned lug 283 and adjustably engaged therewith by the nuts 285.

Said yoke 280 is provided with the elongated apertures 286 and 287 which extend substantially parallel but tend to slightly diverge outwardly, and through which the headed studs 289 and 290 on the oppositely directed lever arms 291 and 292 of the double bell-crank-lever 281 extend normally engaged with the outer ends of said apertures 286 and 287.

The double bell-crank-lever 281 is mounted to rock on the pintle 293 and has the forwardly extending lever arm 295 connected by the stud 296 with the link 297 having its rectangular end 298 slidably engaged for longitudinal adjustment on the push and pull rod 299, which, as shown in Fig. 16 is diametrically disposed and supported to slidably reciprocate in the annular mounting 173 at the outer end of the accessory table arm, and which is conveniently provided with the knob 300 by which said table arm may be manually moved into different desired positions about the axis of its supporting standard.

Said push and pull rod 299 is adjustably secured to the link 297 by the set screw 301 and is limited in its longitudinal movement by the loosely fitting sleeves 302 and 303 preferably formed of insulating material and protecting said rod and preventing possible rubbing contact with the electric wires leading through the table arm.

It will be obvious from the immediately foregoing description of the accessory table arm locking and releasing mechanism that when it is desired to move the table arm toward the operator or observer, a pull on the knob 300 longitudinally moves the push and pull rod 299 to effect rocking

of the double bell-crank-lever 281 in a clockwise direction whereupon the stud 289 engages the outer end of the elongated aperture 286 and pulls the yoke 280 forward with respect to the length 5 of the table supporting arm 170 or to the right with respect to the illustration in Fig. 16, while the stud 290 moves oppositely in the elongated aperture 287.

Such actuation of the rod 299 and yoke 280 10 effects, through the connecting rod 279, rocking action of the bell-crank-lever comprising the arms 276 and 277 in the direction of the arrow in Fig. 32 to force the plunger bolt between the locking balls, thus forcing them apart and rendering them inactive, and consequently permitting the table arm 170 to freely swing into different positions, as may be desired.

Likewise, however, the table arm may be similarly released by manually pushing on the knob 300 which effects rocking of the yoke 280 in an anti-clockwise direction, so that the stud 290 engaging the outer end of the elongated aperture 287 pulls the yoke forward while the stud 289 moves oppositely in the elongated aperture 286. Thus it will be seen that by either pushing or 25 pulling the knob 300, the connecting rod 279 is moved longitudinally in the direction as indicated by the arrow in Fig. 16, and a consequent release of the brake mechanism is effected to permit free movement of the table supporting arm 170.

Water supply to the water niche, cuspidor and various water dispensing devices is directed into the pedestal through the water supply pipe 305, see Fig. 5, which extends upwardly through the 30 floor and into the base section 1 and is secured to the base platform 10 by the fitting 306 and nut 307, and which terminates in a reduced threaded projection 309 to which a coupling 310 is threadedly attached.

Said coupling 310 comprises the stuffing-box 311 containing the packing 312 and the gland nut 313 through which the lower end of the pipe 315, which conveys water through the pedestal, extends and by which it is connected in watertight 40 relation to the water supply pipe 305.

The water pipe 315 extends upwardly through the pedestal and is connected with the main water controlling valve 316 which, as best shown in section in Fig. 27, comprises the inlet passageway 317 leading into the valve chamber 319 and controlled by the valve plug 320 which is arranged to cooperate with the valve seat 321, and which has the valve stem 322 in threaded engagement with the bore 323 of the body of said valve 316.

Said valve stem 322 extends through the packing 325 of the stuffing box 326 including the gland 327 and gland nut 329 and is provided with the controlling handle or knob 330 which is engaged on the squared end 331 of said stem 322 by the knob retaining screw 332.

As shown in Figs. 7 and 27, the body of the valve 316 extends through a suitably provided aperture in the side wall 19 of the main body section 2 of the supporting standard and has the wings 335 and 336, see Fig. 7, which are secured to the annular boss 337 on said side wall 19 by the tap screws 339 and 340.

As shown in Fig. 27, said valve 316 has the passageway 342 connected with the valve chamber 319 and extending through the internally threaded spout 343 to which the threaded nipple 345 is attached. The nipple 345 is connected by the coupling-fitting-nut 346, of well known construction, with the water niche supply pipe 347 which extends upwardly through the pedestal,

see Fig. 8, and is connected, as best shown in Fig. 14, through the nipple 349 and its coupling-fitting-nut 350 with the valve chamber 351 in the water niche controlling valve 352.

The valve chamber 351, as best illustrated in Fig. 8, is connected, as best shown in Fig. 14, by the nipple 353 and its coupling-fitting-nut 355 with the pipe 356 extending upwardly through the water niche and cuspidor section 3 to the water niche spigot 357 which has its spout 359 directed downwardly through the ceiling 360 of the water niche formed by the concave wall 361 which substantially conforms to the upwardly extending rear flange 362 of the water niche basin 363, said spigot being positioned to direct water in the water glass or tumbler 365 which rests upon the removable water niche drain cover plate 366, said tumbler being illustrated by dot-and-dash lines for convenience of illustration.

Flow of water through the spigot 357 into the water niche is controlled by the valve plug 369 which is manually actuated by turning the outwardly projecting knob 370 and which cooperates with the valve seat 371 upon the opposite sides of which the pipes 347 and 356 connect with the valve chamber 351, the inlet pipe connecting through the nipple 353 with said valve chamber 351 forward of the valve seat 371 and the outlet pipe 356 being connected through the nipple 359 with the valve chamber 351 rearwardly of said valve seat 371.

As best shown in Fig. 14, the concave wall 361 has its lateral margins 372 extended rearwardly in relatively parallel planes and respectively turned outward to form laterally directed flanges 373 which provide means for attaching said wall 361 to the bosses 375 and 376, see Fig. 3, on the forward posts or risers 40 of the water niche and cuspidor mounting section 3.

The water niche controlling valve 352 includes a rearwardly extending enlarged body 377 provided with a drain pocket 378 having the laterally extended wings 379 by which said valve 352 is attached to the water niche and cuspidor mounting section 3, and supported in the recess 47 by the screws 380 engaged in the threaded apertures 381.

The water niche basin 363 may preferably be formed of glass or other suitable material having a transversely elongated dished recess 382 forming the forward rim 383 as illustrated in Figs. 8 and 14, and having the counter recess forming the annular seat 385 arranged to receive the drain cover plate 366, beneath which depends the water niche basin drain outlet 386 directed into the drain pocket 378 from which waste water is directed through the noise prevention trap 387 and the pipe 388.

Said water niche basin 363 is provided with the wings 389 extending outwardly from its ends and resting upon the lugs 390 projecting forwardly from the forward posts or risers 40 of the water niche and cuspidor mounting section 3, and said basin is secured thereto by the tap bolts 391.

The cuspidor supporting arm 392 is arranged to revolve horizontally about the vertical axis of the composite supporting standard, and is mounted for support upon the component water niche and cuspidor mounting section 4, see particularly Figs. 3, 10, 11, 12 and 13.

Said cuspidor supporting arm 392 comprises the frame having the substantially flat horizontal plate 393 provided with the bosses 394 and 395 and merging at its perimeter into the depending apron forming the side walls 396 and 397 con-

nected forwardly by the semicylindrical end wall 399 at the outer free end thereof and terminating inwardly or rearwardly in the abutments 400 and 401 disposed upon the diametrically opposite end portions 402 and 403 of the concave semi-annular channeled inner rim 405 of said frame plate 393.

As best shown in Figs. 8, 11 and 13, the channeled rim 405 is fitted to closely embrace the bearing rib 49 encircling the water niche and cuspidor mounting section 3 being free however to slide thereon to permit the cuspidor arm to revolve thereabout, and said rim 405 is maintained in proper engagement with said rib 49 which provides a supporting track therefor, by the strap 406 preferably formed of spring metal and having its end margins turned outwardly, see Fig. 11, to form attaching lugs 409 and 410 abutted against the cuspidor frame abutments 400 and 401 and engaged therewith by the screws 411 and 412, the intermediate bowed portion 413 of said strap engaging the outer cylindrical surface of the rib 49, as best shown in Figs. 11 and 13.

As illustrated in Fig. 11, the swinging movement of the cuspidor arm 392 is limited to about ninety degrees by the stop lug 415 which projects radially from the cylindrical wall 37 of the water niche and cuspidor mounting section 3, into the path of the lugs 419 and 420 which project upwardly from the upper horizontal wall of the semi-annular rim 405.

As best shown in Fig. 11, the frame plate 393 is provided with the aperture 423 extended through the boss 394 and the aperture 425 extended through the boss 395, and said plate 393 is also provided with the opening 426 through which the cuspidor 429 may be connected with the drain or waste outlet, and said plate is recessed downwardly centrally along the inner edge of said opening 426 to provide the attaching shelf 430 to which the cuspidor drain conduit 431 is secured by the screws 432, see Figs. 11 and 13, in engagement with the threaded apertures 433 in the winged attaching pad 435, see Fig. 15.

As shown in Figs. 11, 14 and 15, the drain conduit 431 is provided with the winged attaching pad 436 having the apertures 437 through which screws 439 extend in threaded engagement with the lower horizontal wall of the semi-annular rim 405.

At the forward end, said cuspidor drain conduit 431 is provided with the externally threaded upwardly extended nipple 442 providing an inset annular shoulder 443 upon which the hub 445 of the cuspidor bowl 429 rests with the interposed annular gasket 447 of water resistant resilient material, which is compressed to insure a watertight seal by the annular nut 449 having the in-turned flange 450 engaged with the groove 451 in the outer cylindrical wall of said hub 445.

The inner end of the cuspidor drain conduit 431 curves about the axis of the supporting standard and has the threaded apertures 452 and 453 respectively in its upper and lower walls and coaxial with said standard axis, the uppermost aperture 452 being provided with a nipple fitting 455 to which the water niche drain pipe 388 leading from the water niche basin drain pocket 378 is attached by the connection unit 456 in a well known manner, the lowermost aperture 453 being provided with a nipple fitting 457 which is connected by the fittings 465 and 466 with the drain or waste pipe 462, as illustrated in Fig. 8.

The drain or waste pipe 462 extends downwardly through the supporting standard preferably being coaxial therewith and is connected

with the drain or waste outlet pipe 469 which extends upwardly through the floor and into the base section 1, as shown in Fig. 5. The opposed ends of said drain or waste pipes 462 and 469 are secured for firmness to the platform 10 of the base section 1 by the fitting 470 and nut 471 and convey the waste drainage from the cuspidor bowl 429 and water niche basin 363.

As shown in Figs. 10, 11 and 13, the cuspidor supporting arm includes a readily removable and replaceable casing comprising the half-sections 472 and 473 having their respective horizontal top walls 475 and 476 and their respective in-turned edge margins abutted along a vertical plane passing through the axis of the supporting standard including the frame section 3 and the cuspidor 429, and being retained in any suitable manner, such, for instance, as shown in Fig. 11 wherein the forward or left hand ends of said half-sections have their in-turned edge margins 477 and 478 respectively engaged between the lugs 479 and 480, while the inner or right hand ends of said half-sections have their in-turned margins engaged with the depending extension 485 of the bracket 486 which extends outwardly from the strap 406, see Figs. 11 and 13, and to which said half-sections are engaged by the screws 489 and 490.

As best shown in Fig. 13, the cuspidor supporting arm 392 carries the annular band 492 having its in-turned flange 493 supported on the flat horizontal frame plate 393 by the suitably spaced springs 495 which encircle the headed posts 496 in threaded engagement with the plate 393. Said band 492 is forced upwardly by said springs 495 to engage its upper edge with the under surface of the cuspidor bowl 429 and to thereby close the space between the cuspidor and upper edge of the casing comprising the half-sections 472 and 473.

As shown in Figs. 11 and 12, the side walls of the casing sections of the cuspidor supporting arm are maintained in proper spaced relation by the abutments 400 and 401 and by the vertically extending ribs 499.

The valve 316 is connected by the flexible tube 500 with the fitting 501 which is secured to the drain conduit 431, and which is connected by the pipe 502 with the valve body 503 by the coupling 504. Water distribution to the several parts and implements carried by the cuspidor supporting arm is effected through the valve block or body 503 from which water is conveyed through the pipe 505 to the cuspidor, through the pipe 506, to the water heater, and through the pipe 507 to the saliva ejector, as will be later described.

Water that is conveyed from the valve body 503 through the pipe 505 is controlled by a combination valve-plug and seat of well known construction, which is arranged to be actuated by the valve controlling knob 509 to direct, retard or stop, as desired, the flow of water through said pipe 505 which is extended upwardly through the aperture 425 in the frame plate 393 and through the cylindrical upright housing 510 and extends horizontally through the pipe shielding arm 512 which is directed forwardly and at the free end of which the water conveying pipe 505 is connected to the cuspidor flush nozzle 513 by the swivel joint 515. As shown in Fig. 10, said flush nozzle 513 is directed downwardly into the cuspidor bowl 429 adjacent to the in-turned edge 516 of said bowl and has its free end portion 519 curved into a horizontal outlet 519 so as to direct water spirally over the floor 520 of the cuspidor bowl 429.

Water that is conveyed from the valve body 503 through the pipe 507 is controlled by a valve-plug and seat of well known construction which is arranged to be actuated by the valve controlling knob 525 to control the flow of water to mechanism of water ejector type which may be housed within the cylindrical upright housing 510 and which is arranged to produce suction in the saliva conveying pipe 526 and effect discharge of saliva through the discharge pipe 527 into the cuspidor drain conduit 431.

The saliva conveying pipe 526, as shown in Fig. 11, is connected with a chamber 529 in the projection 530 which extends forwardly from the forward end of the cuspidor drain conduit 431, and said chamber is connected by the connection nipple 532 and fitting 533 through the flexible saliva conveying tube 536, see Figs. 10, 12 and 13, with the saliva ejector 537 which, as shown in Fig. 10, may be conveniently supported, when not in use, upon the saliva ejector bracket 539.

As shown in Figs. 1, 10, 11, 12 and 13, said bracket 539 projects outwardly from the forward end of the cuspidor supporting arm and is secured by the screws 542 to the forward semi-cylindrical end wall 399 of the apron that depends from the frame plate 393, of the cuspidor supporting arm, and said bracket 539, as shown in Figs. 11 and 13 has the circular aperture 543 through which the flexible tube 536 is adapted to extend when the saliva ejector is lifted and drawn outward by the operator to be inserted into the mouth of the patient that may be seated in the chair, the base 545 of which is indicated by the dot-and-dash lines in Fig. 1.

As shown in Figs. 10, 11 and 13, the aperture 543 is formed of two relatively different diameters and consequently provides a convenient annular shoulder 546 upon which the enlarged body 547 of the saliva ejector 537 may normally rest when not in use, with its flexible connecting tube 536 looped as particularly illustrated in Fig. 10.

The pipe 506 conveys water from the valve block or body 503 to the water heater reservoir 550 and is removably connected with its inlet nipple 552 by the connection fitting nut 553. The water after being heated by contact with the electrical heating element 555 within the water heater reservoir 550 is discharged therefrom through the nipple 556 and pipe 557 which is connected therewith by the connection fitting 560.

The flow of warmed water from the water heater 550 is controlled by the valve 561 to which said water heater 550 is connected by the pipe 557 and said flow is arranged to be regulated by the manipulation of the controlling knob 562, which not only controls the flow of warmed water through the outlet fitting 563 of the valve 561, but is also arranged to control the flow of water of normal temperature, or what is generally termed cold water, through said outlet. The cold water is supplied to the valve 561 through the pipe 565 which connects said valve with an upwardly extended branch outlet fitting 566 in the nipple 552, as best shown in Fig. 11.

The valve outlet fitting 563 is connected by the looped flexible tube 569 with the water syringe 570, of well known construction, which, as best illustrated in Fig. 10, is normally supported by the cylindrical water syringe warming holder 571 comprising the outer cylindrical casing 572, which is attached to the boss 394 on the frame plate 393 and projects upwardly from the top wall 475 of the cuspidor supporting arm casing comprising the casing sections 472 and 473.

As illustrated in Fig. 10, the lower or inner portion 575 of the syringe body 576 depends into the bore 577 of said syring warming holder 571, and said syringe may be freely withdrawn therefrom for use in directing water into the patient's mouth, such withdrawal causes the looped flexible tubing to be drawn upwardly through the bore 577 of the syring warming holder 571 until the weighted stop 579, which is adjustably disposed on the flexible tube 569, abuts against the lower end of the inner cylindrical concentric tube 580 of said warming holder, see Figs. 29 and 30.

Said weighted stop not only serves to limit the length of flexible tube 569 that may be withdrawn through the bore 577, but also tends when substantially fully extended, to serve, by its weight, to automatically retrieve said flexible tube when the operator relieves the pull thereon in his effort to replace the syringe 578 in its holder 571.

As shown in Fig. 30, the inner cylindrical tube 580 of the syringe warming holder 571 depends through the aperture 582 in the boss 394 and is provided intermediate of its length with the annular attaching flange 583 which rests upon the heat insulating washer 585 on the top wall 475 of the casing section 472 and is secured to said annular boss 394 on the plate 393 by the screws 586 and 587 extended through suitably aligned apertures in said flange 583, in said top wall 475 and into suitably provided apertures 589 and 590 in said annular boss 394, being rigidly secured therein by threaded engagement with the headed bushings 592 and 593 extended upwardly into said apertures 589 and 590.

The upper end of the tube 580 is externally threaded and has the cap ferrule 595 threadedly engaged therewith and is also in threaded engagement with the upper end of the outer cylindrical casing 572, the lower end of which terminates in the enlarged base 596 which embraces the flange 583 and conveniently conceals the heads of the screws 586 and 587.

As shown in Fig. 29, the annular space between the outer cylindrical casing 572 and the inner cylindrical tube 580 is arranged to receive the heating element 599 including the leading-in wires 600 and 601 which are protected from accidental contact with said casing 572 and tube 580 by the sleeves 602 and 603 formed of insulation material.

The wires 600 and 601 extend downwardly through the apertures 605 and 606 in the flange and the aperture 582 in the boss 394 and top plate 393 of the cuspidor supporting arm frame, and said wires 600 and 601 extend outwardly through said frame and casing to the binding screws 609 and 610 respectively on the relatively insulated metal connection plates 612 and 613 which are mounted on the bracket 615 secured to the outer rim margin of the top plate 393 by the screws 616.

The connection plates 612 and 613 are respectively provided with the binding screws 619 and 620 which are connected by the wires 622 and 623 with the electric heating element 555 which extends into the water heater reservoir 550 but which has its wire connection means projecting slightly outward from the forward end of said water heater reservoir, said electric heating element being secured in the water heater reservoir by the nut 625.

As shown in Fig. 11, electric current is supplied to the connection plates 612 and 613 by the wires 626 and 627 which are connected to the binding screws 629 and 630 and lead therefrom through the cuspidor supporting arm and upwardly

through the pedestal structure and through the temperature control switch 159 downwardly to the transformer 631 which is disposed in the water niche and cuspidor mounting section 3, as shown in Fig. 8.

5 The bracket table arm 170 comprising the annular mounting 173 has mounted thereon the displaceable table supporting ring 628 adapted to carry the bracket table 632 having the table tray 10 633 supported thereon, as shown in Figs. 1 and 2, which table is of the type shown and described in United States Letters Patent No. 1,972,072, and therefore the details of said table are not herein shown and described. However, said table, as 15 shown in said patent, includes such accessories as air syringe, air cutoff, illuminated mouth lamp, and cautery and pulp tester, all of which are to be connected, through said table arm 170 and the composite supporting standard or pedestal, with suitable sources of fluid and electric current supply.

As shown in Figs. 1 and 2, the bracket table arm 170 carries the gas burner 635 which is protected from air currents by the shield 636 and which 20 may preferably be supported over the margin of the table 632 and its tray 633 by the hollow horizontally disposed gas conveying arm 637 which is connected to and supported by the gas conveying tube 639 upon which it may revolve away from the table 632 and tray 633. Said gas conveying tube 639 is provided with the gas controlling valve 638 at its upper end and terminates at 25 lower end in the hollow connection fitting 640 see Fig. 16, which has the upwardly projecting threaded stud 642 extending through a suitably provided aperture in the inwardly extending rib 643 of the side wall 171, and said fitting is engaged therewith by the nut 645 threaded on said stud 642.

30 Gas is conducted to the fitting 640 for consumption at the tip 634 of the burner 635, from the gas service pipe 646 which extends upwardly through the floor and is rigidly secured to the platform 10 of the base frame section 1 by the fitting 647 and nut 648, see Fig. 5, and to which connection is made by the union nut coupling 649 with the pipe 650 extending upwardly through the main body section 2, water niche and cuspidor section 3, accessory table arm section 4, and into 35 the dome or motor section 5 where it is connected by the union nut 651 with the inlet of the gas controlling valve 161, as shown in Fig. 24. As shown in Fig. 22 said valve 161 has the inlet passageway 652 and the outlet passageway 653 between which the valve plug 654 and its valve seat 655 cooperate to control the flow of gas therethrough when the control knob 162 on the stem of said valve plug 654 is manually adjusted.

40 The outlet of said valve 161 is connected by the union nut 656 with the pipe 657 which in turn is connected by the union nut 659 with the nipple 660 extending from the fitting 662 inwardly through the upwardly extending wall of the hub 54. Said fitting 662 is connected by the flexible tube 665 which, as shown in Fig. 17, is spirally coiled clockwise and supported to slide upon the annular shelf 62, with the gas and air connection block 666, the foot 667 of which rests upon the bearing mounting 175 of the bracket table arm 170 and is rigidly secured thereto by the screw 669.

45 As shown in Fig. 17, the spirally disposed flexible tube 665 is provided with the metal tip 670 which may be inserted into the fitting 662 and 50 secured thereto in fluid-tight relation in any

suitable manner, as by solder, and said tube is provided at its opposite end with the metal tip 672 which may be similarly attached in fluid-tight relation to the L-fitting 675.

As best shown in Fig. 19, the L-fitting 675 has the socket 676 arranged to receive the tip 672 and from which the passageway 677 extends and terminates in the laterally extending outlet 679 surrounded by the annular flange 680 which is coaxial with the hemispherical body 682 of said L-fitting.

As shown in Fig. 19, the L-fitting 675 is removably disposed in the thimble 683 which has the lateral slot 685 in its cylindrical wall extending parallel with its axis, and the annular groove 686 in its inner end wall 687 arranged to receive the annular resilient gas resistant packing 689 which surrounds the axially aligned outlet aperture 690, and against which said annular flange 680 is forced in fluid-tight relation by the threaded plug 691 which is concaved to conform to the hemispherical body 682 of said L-fitting 675 and which has its threads 692 engaged with the internally threaded head 693 of said thimble 683.

Referring again to Fig. 19, the thimble 683 is engaged, in fluid-tight relation, preferably by solder, in the circular pocket 695 in the connection block 666, with its head 693 engaged with the outer face of said connection block so that its inner end 687 is slightly spaced from the inner end wall 697 of said pocket 695, thus providing the chamber 699 which serves to connect the aperture 690 with the outlet passageway 700 in said connection block 666.

With particular reference to Figs. 16, 17, 19 and 20, the outlet passageway 700 extends downwardly in said connection block 666 and outwardly in the foot 667 of said block and is connected therein with the pipe 701 and by the connection fitting 702 and union nut 703 said pipe 701 is detachably connected with the pipe 705 leading through the bracket table arm 170 and connected with the hollow connection fitting 640 of the gas burner support.

Instruments in the bracket table 632 that require compressed air for their operation may be supplied from the air service pipe 707 which extends upwardly through the floor and is rigidly secured to the platform 10 of the base frame section 1 by the fitting 709 and nut 710, see Fig. 5, and to which connection is made by the union nut fitting 712 with the pipe 713 extending upwardly through the main body section 2, water niche and cuspidor section 3, accessory table arm section 4 and into the dome or motor section 5 where it is connected by the union nut 714 with the inlet of the valve 163, and controlled by the knob 164. As shown in Fig. 23, said valve 163 has the inlet passageway 715 and the outlet passageway 716 between which the valve plug 717 and its valve seat 718 cooperate to control the flow of air therethrough when the control knob 164 on the stem of said valve plug 717 is manually adjusted.

As illustrated in Figs. 24 and 26, the compressed air valve 163 includes the laterally extended bracket 719 terminating in the circular band 720 which embraces and supports the compressed air filter 721, and said bracket 719 has the outlet passageway 716 of the valve 163 extending therethrough and is arranged to convey compressed air from said valve 163 directly into said air filter 721.

The air filter 721 has its air outlet 723 connected by the union nut 725 with the pipe 726

which is connected by the union nut 727 with the inlet 729 of the pressure regulator 730 which is supported on the control panel 166 by means of the interposed bracket 732 secured to said panel by the screws 733, and as said pressure regulator is of a type in commercial use, its details of construction are not herein set forth.

The outlet 735 of the pressure regulator 730 is connected by the union nut 736 with the pipe 737 which is connected by the union nut 739 with the nipple 740 extending from the fitting 742 inwardly through the upwardly extending wall of the hub 54. Said fitting 742 is connected by the flexible tube 745 which, as shown in Fig. 17, is spirally coiled anti-clockwise and supported to slide upon the flange 58, with the air and gas connection block 666.

As shown in Fig. 17, the spirally disposed flexible tube 745 is provided with the metal tip 746 arranged to connect said flexible tube 745 with the fitting 742, and the metal tip 749 by which it is connected with the L-fitting 750, which is similar in detail to the L-fitting 675 above described and shown best in Fig. 19, and said L-fitting 750 is removably retained in the thimble 752 by the screw-plug 753 in threaded engagement with the head 755 of said thimble 752, as shown in Fig. 18.

Referring particularly to Fig. 18, the air passageway 756 in the L-fitting 750 is connected through the inner wall of the thimble 752 with the outlet passageway 757 which extends downwardly through said connection block 666 and outwardly through its foot 667 and is connected by the pipe 759 through the connection fitting 760 and union nut 761 with the pipe 762, which, as shown in Fig. 16, leads into the annular mounting 173, from where it may be extended into the bracket table 632 for connection with the air dispensing implements therein contained.

The air filter 721, shown in Figs. 21, 24, and 26, is designed to extract moisture from the compressed air before said air enters the pressure regulator 730, and the accumulation of trapped water in said filter may be periodically drawn off from the lower end of said filter through the discharge pipe 763 which extends downwardly through the pedestal and terminates in the air line water relief valve 765 which is engaged with the side wall 19 of the main body section 2 by the nut 767.

As best shown in Fig. 28, said valve 765 is provided with the valve plug 769 arranged to be rotated to engage or disengage its conical inner end 770 with the valve seat 771. Said valve plug 769 has the knurled band 772 by which it may be rotated and is provided with the passageway 773 extending therethrough for the discharge of water from the filter 721, conveyed by the pipe 763 which is connected with said valve 765 by the gland-nut 775.

As shown in Fig. 4, the resistor panel 776 is attached to the transverse wall 23 of the main body section 2 by the screws 777 and is provided with the resistors 779, 780, 781 and 782 removably supported by the clips 785 and 786, of well known construction, respectively embracing said resistors at the top and bottom thereof and facilitating their convenient removal and replacement.

Said resistor panel 776 is provided with the main terminals 789 and 790 to which the line wires 791 and 792 of the leading-in cable 793 are attached, and supply the electric current that

is employed throughout the entire unit assemblage.

Directly below and closely associated with the resistance panel 776, the controller slip-joint receptacle 795 is attached to the transverse wall 23 by the screws 796 and said slip-joint receptacle is connected by the insertable and removable plug 797 and cable 799 with the foot controller 800 having the foot actuated pedals 801 and 802, as shown in Fig. 1.

Said foot controller 800 is of a well known type and is arranged to not only control the direction of rotation of the armature 95 of the electric motor 96 in the motor or dome section 5, but to also vary its speed of rotation.

The slip-joint receptacle 795 includes the several plug sockets 803, 804, 805, 806, 807, 808, 809 and 810, which are arranged to receive corresponding plug projecting pins in the removable plug 797 to complete certain electric circuits determined and controlled by the position of the foot pedals 801 and 802, said plug sockets being connected by suitable wiring connections with the resistor panel 776.

As shown in Fig. 4, the resistor panel 776 is also provided with the terminals 812, 813, 814, 815, 816, 817, 818 and 819, and is connected through the cable 29 including the several wires therein with the transformer 631 comprising the coils 826 and 827 connected at the top and bottom thereof by the yokes 829 and 830 which are respectively attached by the screws 831 and 832 to the rear posts or standards 40 of the water niche and cuspidor section 3. Said transformer includes the oppositely disposed lateral terminal bars 835 and 836 respectively attached by the screws 838 and 839 to the opposite ends of the yokes 829 and 830.

With continued reference to Fig. 4, the terminal bar 835 is provided with the connection terminals 840, 841, 842, 843, 844, 845 and 846, and the terminal bar 836 is provided with the connection terminals 850, 851, 852, 853, 854, 855 and 856, to which wires connecting the various instruments, implements and devices employed on the unit and requiring modification of the line wire current may be connected.

The electric current entering the unit through the line wires 791 and 792 passes to the main switch 155 in the dome section 5 by which said current may be turned on or off at the will of the operator, and from which switch said current is conveyed by suitably provided wiring to the various controlling and indicating stations including the pilot light 165, the low voltage switch 157, and the protecting fuses 860, 861, 862 and 863.

As shown in Fig. 26, the fuses 860, 861, 862 and 863 are supported on the fuse panel 864 which is mounted in the dome section 5, and are removably and replaceably held by the spring clips 865 and 866 respectively at the top and bottom thereof. Said fuse panel 864 is provided with the vertically disposed terminals 870, 871, 872, 873, 874 and 875 thereon, and the horizontally disposed terminals 880, 881 and 882, all of which are included in the wiring system within the unit.

The temperature control switch 159 is connected through suitable wiring connections to control the temperature of the water in the water heater reservoir 550 which is disposed within the cuspidor arm, and also in the water syringe holder 571. The temperature of the water may be increased in varying degrees by turning the

control knob 160 of said switch in clockwise direction from the off position.

However, if it is desired that cold water be delivered through the syringe 570, the valve controlling knob is turned to shut off the warm water directed from the water heater reservoir 550 through the pipe 551, and is actuated to open the by-pass pipe 565 to permit water from the cold water supply pipe 506 to be directed thereby to the syringe.

Water may be completely shut off from both the water heater reservoir 550 and the syringe 570 by the valve 508 which depends from the valve block or body 503 and is arranged to control the flow of water from said block through the pipe 506 to said water heater reservoir 550.

As best shown in plan view in Fig. 16, the table arm 170 is arranged to revolve about the axis of the supporting standard through an arc of approximately one hundred and five degrees (105°), and conveniently mounted on the forward side bar 172 is the electric selector switch 890 for controlling the cautery and pulp tester in the table not herein shown.

The selector switch 890 shown in Figs. 16 and 37 is mounted on the sleeve 891 which is threadedly engaged in the side bar 172, and comprises the terminal block 892 formed of insulating material and provided with the terminals 893, 894, 895 and 896, and said switch includes the shaft 897 carrying the movable contact finger 898 on its inner end arranged to sweep across the inner projecting end contacts of the terminals 893, 894 and 895 and to selectively connect them with the terminal 896 through the shaft 897 and conductor plate 899, said contact finger 898 being adjustable to selectively connect said terminals by the switch handle 900 projecting from said bracket arm toward the operator's normal position.

The terminals 893, 894 and 895 of the switch 890 are respectively connected, as shown in Fig. 16, by the wires 901, 902 and 903 to the booster transformer 905 and the terminals 893 and 896 are respectively connected by the wires 906 and 907 through the slip joint connector comprising the plug 909 and socket 910, and corresponding wires in the cable 912, with the instrument handle, which is normally located in the bracket table 632, and which is arranged to carry instruments such as a cautery or a pulp tester.

Said booster transformer 905 is also connected by the wires 913 and 914 through the plug 909 and socket 910 and cable 912 with the instruments in the bracket table, and is so designed as to be incapable of delivery from the secondary coil of sufficient energy to detrimentally affect the cautery which normally does not require more than about four-and-one-half (4½) volts, or the mouth lamp which may be connected in the cautery handle and which normally would not require over five (5) volts.

The function of the booster transformer 905 is to increase the voltage of the electric current from the transformer 631 comprising the coils 826 and 827 in the water niche section 3. This increase in voltage is required for testing vitality of teeth by reaction to electric impulses. The amount of electric current required for this purpose is necessarily limited, for that reason the booster transformer 905 particularly designed to produce a limited output of energy is employed.

The transformer in the water niche section 3, and shown in Figs. 4 and 8, normally carries a voltage of six volts, and the booster as designed

increases this voltage by three times in one step incident to the movement of the contact finger 898 from the terminal contact 893 to the terminal contact 894, see Fig. 37, and increases the voltage by ten times in the movement of said contact finger 898 from the terminal contact 894 to the terminal contact 895.

Owing to the limitation of energy as above noted, neither the cautery nor the mouth lamp can be damaged, even though the contact finger 898 be on the contact point of the terminal 894 or 895. This limited energy is accomplished primarily by the small amount of iron in the magnetic circuit and by use of high resistance for the booster transformer primary winding.

Wires that connect the various terminals located within the pedestal with terminals located in the bracket table or other accessories carried by the bracket table arm 170, may be included in the cables 915 and 916 which are detachably connected within said bracket table arm by the slip-joint connector comprising the plug 917 and socket 918.

The bracket table arm 170 is provided with the outlet receptacle 919 secured thereto by the screws 920 and having its wires 921 and 922 connected with the terminals 923 and 924 of the terminal plates 925 and 926 which are carried by the terminal block 927 formed of suitable insulation material, which is secured to the transverse supporting bar 928 by the screws 929.

The terminal plates 925 and 926 are provided with the terminals 930 and 931 to which the wires 932 and 933 of the electric cord 935 are connected, which electric cord extends through the bracket table arm and pedestal to suitably provided line wire current terminals therein. Said terminal plates 925 and 926 are also provided with the terminals 936 and 937 to which the wires 938 and 939 are connected and extend in the electric cord 940 through the annular mounting 173 upwardly and said wires 938 and 939 are arranged to be connected to the variously disposed accessories which are mounted upon said bracket table arm, and require line wire current for proper functioning.

Mounted in the forward side bar 172 of the bracket table arm frame 170 is the signal switch 941 having the push-button or call button 942 arranged to be connected by the wires 943 and 944 with the terminals of an annunciator or other suitable signal which may be remotely located and therefore not shown; said wire 943, as shown in Fig. 16, may be spliced as at 945 with the wire 913 and thereby connected through the plug 909, socket 910, the cable 912 and other suitable connections with one of said signal terminals, and the wire 944 is directly connected with the plug 909 and through the socket 910, cable 912 and other suitable connections with the other of said signal terminals.

The supporting standard which is composed of the several frame sections 1, 2, 3, 4 and 5 is encased in a housing formed of a plurality of semi-cylindrical housing or casing sections which may be readily assembled and removed and which are so yieldingly retained in assembled relation to form the pedestal structure, that they may separate to a predetermined extent should any gas that might be accidentally liberated, such as by leakage, be ignited within the housing or casing which forms said pedestal structure, and by such yielding avoid damage or detrimental effect.

As shown in Fig. 3, the base flange 6 is encased by the complementary semianular base

flange housing sections 950 upon which the semi-cylindrical base housing sections 951 having the opposed inturned lateral edge flanges 952 are superposed. The opposite semicylindrical margins 953 and 954 of said housing sections 951 are inset, see Fig. 5, and form regions of reduced diameter in the pedestal of the assembled structure, as illustrated in Fig. 2.

That portion of the pedestal comprising the complementary semicylindrical housing sections 955 that encase the main body frame section 2 is shown in Figs. 3, 7 and 39 and is typical of the several housing sections that comprise the pedestal casing structure, said housing sections 955 each having opposed inturned flanges 956 and 957, the flange 956 of each of the housing sections 955 being interrupted by the semicircular recesses 959 and 960 which cooperate to form circular apertures, through which the valves 765 and 316 project, as best shown in Fig. 7, when the complementary housing sections 955 are assembled with said flanges 956 and 957 in relatively abutted relation.

As best shown in Fig. 7, the housing sections 955 have their flanges 956 and 957 reduced in width at their upper and lower ends to provide the restricted regions 961 and 962 which are engaged in the notches 35 and 36 in the flanges 21 and 22 respectively.

Said sections 955 are inset below the flange 21 and above the flange 22 to provide the reduced semicircular end margins 963 and 964 which, as shown in Fig. 2, cooperate to form regions of reduced diameter in the assembled structure, and as shown particularly in Fig. 39, the reduced regions are provided with the circularly elongated slits or apertures 965, the purpose of which will be hereinafter described.

The upper or water niche portion of the cuspidor and water niche frame section 3 is arranged to be encased by the housing sections 966 and 967 respectively having the relatively abutted in-turned lateral marginal flanges 968 and 969, as best shown in Fig. 14, which are arranged to be detachably engaged in the notches 52 disposed in diametrically opposite relation in the flange 39, and also engaged in the diametrically opposite notches 53 in the upper flange 43 of said frame section 3, see Fig. 9.

As shown in Figs. 8 and 14, the forward housing section 967 is provided with the substantially rectangular aperture 970, the edge margins of which are protected by the channeled frame 971 through which aperture the water niche basin 363 projects forwardly and which readily permits withdrawal and replacement therethrough of the water glass or tumbler 365, normally resting upon the drain cover plate 366, as shown in Fig. 8, said tumbler being shown in dot-and-dash lines for convenience of illustration.

Similarly, the motor or dome frame section 5 is encased by the complementary semicylindrical housing sections 972 and 973, shown in Figs. 2, 3, 9, 21, 25 and 26, and respectively having the relatively abutted inturned flanges 974 and 975 which as shown in Figs. 9 and 21 are engaged in the notches 976 and 977 in the peripheral outer edge of the annular floor 65 of said motor or dome frame section 5.

As best shown in Figs. 9 and 25, the upper semicircular margins 978 and 979 of the housing sections 972 and 973 are inset and overlap the inset margins 980 and 981 of the semiannular dome or cap housing sections 982 and 983 which have the relatively abutted inturned flanges 985

and terminate short of the semicircular inner edges 986 of the respective dome or cap housing sections 982 and 983.

As shown in Fig. 9, the inner edge margins of the horizontal top wall of said dome or cap housing sections 982 and 983 overlap and rest upon the horizontal ledge 988 of the annular head 69 at the top of the dome or motor frame section 5.

The housing thus described is capped by the annular crown plate 989, see Fig. 9, which is slightly arched, having its outer peripheral edge 990 curved downwardly and engaging the upper wall of the dome or cap housing comprising the housing sections 982 and 983, and having its inner rim 991 curved upwardly and engaging the under surface of the enlarged central portion of the spacer sleeve 74, by which it is retained in its proper position to cover the pocket 70.

As shown in Figs. 9 and 16, the frame of the bracket table arm 170 is arranged to be enclosed in the readily removable and replaceable bracket table housing or casing sections including the main housing section 992, the substantially semicircular inner end section 993, the substantially semicircular outer end section 994, and the flat horizontally disposed bottom plate or closure section 995.

The main housing section 992 forms the flat top cover from which the rearward wall 996 and the forward wall 997 depend in a unitary structure, see Figs. 9 and 17, and have their free lower edge margins 998 and 999 upturned and arranged to reinforce the perimetral lower edges of the forward and rearward walls, which edge margins 998 and 999 conform closely to the opposite edge margins of said bottom plate or closure section 995.

As shown in Fig. 16, the back or rearward wall 996 curves forwardly at its opposite end regions and terminates at the supported end adjacent the pedestal in the inturned flange 01 extending into the notch 02 provided therefor in the forwardly curved inner portion 175 of the rear side bar 171 of the accessory table arm frame 170. Said forwardly curving back wall 996 terminates at its outer end in the inturned flange 03 extending into the notch 04 provided therefor in the outer surface of the annular mounting 173 forming the outer or free end of the accessory table arm 170.

Again with reference to Fig. 16, the inner circular end of the accessory table arm 170 is enclosed forwardly by the inner end casing section 993 terminating at one end in the inturned flange 05 disposed in abutted relation with the inturned flange 01 of the back wall 996. Said casing section 993 terminates at the opposite or forward end in the outwardly turned flange 06 which underlies or extends in back of the inner end of the forward wall 997.

With further reference to Fig. 16, the outer circular end of the accessory table arm 170 comprises the annular mounting 173 and is enclosed forwardly by the outer end casing section 994 terminating at its outer end in the inturned flange 07 disposed in abutted relation with the inturned flange 03 of the back or rearward wall 996.

Referring again to Fig. 16, the several housing sections 992, 993 and 994 are maintained in proper spaced relation to the accessory table arm frame 170 by the several vertically disposed ribs 174 against which said accessory table arm housing sections bear, the main housing section 992 being secured to the frame 170 by the screws 09 and 010, the inner end housing section 993

being secured by the screw 011 and the outer end housing section being secured by the screw 012. The bottom plate 995 is secured to the under surface of the frame of the arm 170 by the screws 013.

As shown in Fig. 9, the space between the upper wall of the accessory table arm housing section 992 and the lower floor 65 of the motor or dome section 5 is enclosed by the casing section extensions 015 depending from the inset regions 016 of reduced diameter of the sections 972 and 973 and having the lower edges inturned to provide the flange 017.

As shown in Fig. 2, the several regions of reduced diameter in the pedestal casing are encircled by the girdling bands 019, 020, 021, 022, 023, 024 and 025, not only serving as a means of utility but of ornamentation, and of which the band 023, shown in perspective in Fig. 41, is typical.

Said girdling band 023, as shown in perspective in Fig. 41, is formed of a strip of suitable material, preferably metal, having a longitudinally extending slot 026 near one end and a circular aperture 027 near the other end of said strip which is arranged to girdle the reduced upper end margin 964 of the housing 955 which, as shown in perspective in Fig. 39, has the circularly elongated apertures 965 into which the inwardly projecting lugs 030 extend. Although I have shown and described apertures 965 arranged to receive the lugs 030, it will be obvious that inwardly depressed regions corresponding to the position of said apertures in the margin 964 may be employed with equal facility.

As shown in Fig. 41, the band 023 is provided with a longitudinally extending groove 032 which serves as ornamentation and, as shown in Fig. 40, said band 023 closely embraces the circular inset margin 964 at the top of the housing section 955, shown in Figs. 39 and 40, with the opposite ends of said band 023 overlapped, the end having the elongated slot 026 being disposed between the margin 964 and the end of the band having the circular aperture 027.

The ends of the girdling band 023 thus overlapped, as shown in Fig. 40, may preferably be yieldingly engaged to hold the housing sections in proper relative position to encase the supporting structure, including the several frame sections, by the screw 033, which may be engaged with the threaded aperture 035 in the housing section margin 964, or otherwise engaged, as may be found most desirable.

As an adjunct to the structure thus described, the table supporting ring 628 may be replaced by the hollow spray bottle warmer supporting arm 036, which is mounted to revolve about the axis of the accessory table 632 on the table mounting bearing 037, which is supported on the ledge 039 in the annular mounting 173 of the accessory table arm 170, as shown in Fig. 43, said arm 036 and table 632 being arranged to independently revolve upon the free end of said accessory table arm, and jointly movable about the axis of the supporting standard or pedestal.

As shown in Figs. 42, 43, 44, 48, 49 and 51, said water warmer supporting arm 036 is provided at its free end with the annular mounting 040 upon which the spray bottle and water tumbler warmer 041 is mounted to revolve. Said warmer 041, as shown in Fig. 48, is provided with the receptacles 042, 043 and 044, respectively arranged to receive the removable and replaceable spray bottles 045 and 046 and the water tumbler

047, shown in Fig. 44, the spray bottle illustrated in side elevation in Fig. 47 being typical of both of those shown in Fig. 44, and comprising the connection nipple 048, the swivel coupling 049 and the nozzle 050.

The body 051 of the spray bottle and water tumbler warmer 041 is provided with the electric heating element 052 having the terminals 053 and 054 and secured thereto by the screws 055, see Fig. 48. Said body is mounted upon the base frame 056 from which it is insulated by the interposed diaphragm 057 of nonconducting material, and secured by the screws 060 extended through the lugs 058 of said base frame 056, said diaphragm 057 being independently attached to the lugs 059 of the body 051 by the screws 061.

The spray bottle warmer body 051, as shown in Figs. 48, 50 and 51, is provided with the shell or casing 062 between which and said body the jacket 065 of heat insulating material, preferably in sheet form, is interposed, and said shell or casing 062 extends downwardly and affords a depending apron which also embraces the base frame 056.

The spray bottle warmer is arranged to independently revolve on its supporting arm 036 which is provided at its outer free end with the inwardly extending rim 066 providing the bearing seat 067 upon which the centrally disposed generally circular spider 069 of the base frame 056 rests for relative rotation, being held in axial position thereon by the annular retainer 070 which rotatably bears against the under face of the inset rabbet 071 in the inner edge of said rim 066, and said retainer 070 is secured to the frame spider 069 by the screws 072.

As shown in Figs. 48, 49 and 51, the base frame 056 is provided with the bottom closure supporting lugs 073 and 074 projecting inwardly and to which the bottom closure plates 075 and 076 may be secured by the screws 077 and 078 to enclose the chamber 079 included between said closure plates and said diaphragm 057, see Fig. 48.

The supply of electric current to the heating element 052 may be manually controlled to turn it on or off as may be desired, and it is also automatically controlled by thermostatically actuated mechanism to maintain a relatively uniform desired temperature.

Said electric current may be introduced into the spray bottle warmer by the electrical conductors 080 and 081 which lead from suitably provided connections and extend through the pedestal, accessory table arm and spray bottle arm 036, as shown in Figs. 49 and 51, and which extend spirally in the semicircular free end of said arm 036 and terminate at the terminals 082 and 083 in the terminal plates 084 and 085, on the terminal block of insulation material 086 which is secured to the spider frame 069 by the screws 087, see Fig. 49.

The electric circuit through the heating element 052 may be made or broken by mechanism including the rocker post 088 which extends vertically through the diaphragm 057 and which is mounted to rock in the bearing bracket 089 which, as shown in Fig. 50, is secured to the under side of said diaphragm 057 and secured by the screws 090 extended therethrough.

Referring again to Fig. 50, the rocker post 088 is provided beneath the diaphragm with the spring contact finger 091 which carries the contact 092 in opposed relation to the contact 093 mounted in stationary relation on the mounting bracket 094 also secured to the underside of said

diaphragm 057 by the screw 095 extended therethrough, which mounting bracket 094 also carries the magnet 096 in opposed relation to the magnet keeper or bridge 097, which is carried by said contact finger 091 as above described.

With further reference to Fig. 50, the rocker post 088 is provided with the lever arm 098 which is connected by the link 099 to the outer end of the bimetallic thermostatic coiled spring or strip 100 which is limited in forward movement by the guide post 101 and is spirally coiled about the rock-shaft 102 journaled in the bearing bracket 103 secured to the underside of the diaphragm 057 by the screws 105.

Said rock-shaft 102, as shown in Fig. 51, carries at its lower end the hubbed disc 106 which is secured thereto by the screw 107, and which carries the rocker-arm or lever 109 having its inner circular end enlarged and encircling the hub of said disc 106 and secured thereto so as to move therewith by the screw 110. The outer circular end 112 of said lever 109 is extended into the rectangular void or recess 113, best shown in Fig. 48, in the rack-bar 115, having the upwardly projecting rack teeth 116.

With reference to Figs. 48, 50 and 51, the rack-bar 115 is arranged to slide longitudinally on the shelf type supporting bracket 117 which is secured to the diaphragm 057 by the screws 119 and depends therefrom, as shown in Figs. 48 and 51. Said bracket 117 has its lower horizontal wing or shelf 120, see Fig. 50, provided with the longitudinally extending apertures 121 and 122 through which the shanks of the screws 123 and 125, threadedly engaged in said rack-bar 115, extend with their respective heads 126 and 127 underlying and loosely engaging the under surface of said horizontal shelf 120 of the bracket 117, and maintaining the rack-bar 115 in sliding contact with the upper surface of said wing or shelf 120.

The teeth 116 of the rack-bar 115 are interengaged with the teeth of the pinion 130 on the inner end of the shaft 131 which is mounted to rotate in the bearing 132 depending from the diaphragm 057 and secured thereto by the screws 133. Said shaft 131 extends rearwardly through the casing 062 and is provided with the controlling knob 135 by which said shaft 131 may be rotated to shift the rack-bar 115 and thereby rotate the rock-shaft 102 to wind or unwind the coiled thermometal strip 100. A pointer 136 arranged to move with said knob 135 indicates the position of the rack-bar 115.

Turning of the controlling knob 135 in a clockwise direction effects winding up of the coiled strip 100 which tends to draw the lever arm 098 and the contact spring finger 091 toward the right hand with respect to Fig. 50 and to effect breaking of the electric contact between the contacts 092 and 093. Turning of the controlling knob 135 in an anticlockwise direction effects unwinding of the coiled strip 100 to produce movement of the contacts 092 and 093 together to complete the electric circuit therethrough to energize the heating element 052.

The coiled strip 100 is disposed in the chamber 139 with the heating element 052 and is arranged to automatically effect actuation of the lever arm 098 and the spring contact finger 091 to separate the contacts 092 and 093 and thereby break the electric circuit in which the heating element is included when the temperature in said chamber 139 rises to a degree pre-

determined by the position of said rack-bar 1115 and variably controlled by the knob 1135.

The terminal 053 of the heating element 052 may be connected through suitable wiring with the terminal 1140 which connects through the contact finger 091, contacts 092 and 093 with the terminal 1141 of the terminal plate 084. The terminal 054 of said heating element 052 may be connected through suitable wiring with the terminal 1143 of the terminal plate 085. As above described, said terminal plates 084 and 085 are connected with the line wires 080 and 081.

As shown in Figs. 42, 43, 44, 45, 46 and 51, the X-ray illuminator 1150 may also be carried by the spray bottle warmer arm 036 and is removably and replaceably attached to the forward side, as illustrated in Fig. 42, of said spray bottle warmer.

The frame 1152 of said illuminator comprises the rearwardly extending support 1153 resting upon the forward bar of the base frame 056 of the spray bottle warmer and is secured thereto by the screws 1155 which extend upwardly through the countersunk apertures 1156 in said base frame 056.

Said frame 1152 supports the illuminator casing comprising the top wall 1159, the bottom wall 1160, both of which curvedly merge into the forward wall 1162, and the end walls 1163 and 1165. Said forward wall 1162 is provided with the window opening 1166 which is surrounded by the window frame 1167, the inner margin 1169 of which overlaps said window opening 1166, and is secured to said forward wall by the screws 1170.

As shown in Figs. 44, 45 and 46, the window opening 1166 is provided with the pane of glass 1172 which is retained in the window opening 1166 by the brackets 1173 disposed oppositely and substantially in alignment with the lower edge of said glass pane 1172 and respectively extending from the end walls 1163 and 1165 and provided with the outwardly projecting lugs 1176 extending beneath the glass pane 1172 and serving to support it, and the outwardly projecting lugs 1177 which extend over the lateral edges of said glass pane to maintain it in proper registry with said window opening 1166.

As shown in Fig. 45, the glass pane 1172 is also retained by the brackets 1179 similarly disposed oppositely in alignment with the upper edge thereof, said brackets 1179 being similar to the brackets 1173 and being provided with the outwardly projecting lugs 1180 extending over the top edge of the glass pane 1172 and the lugs 1181 extending over the lateral edges of said glass pane.

As shown in Figs. 45 and 46, the brackets 1173 and 1179, which may preferably be secured by spot welding to the side walls 1163 and 1165 of the X-ray illuminator casing, are respectively provided with the spring clips 1182, see Fig. 46, which are arranged to bear against the inner surface of the glass pane 1172 to maintain it in the window opening 1166 in contact with the inner overlapping margin of the window frame 1167. The lower bar of the window frame 1167 has the upturned extension 1183 providing a convenient support for holding a film before the glass pane 1172.

As shown in Figs. 44, 45 and 46, the X-ray illuminator is provided with the reflector comprising the complementary concave reflective sections 1185 and 1186 respectively having op-

positely directed outwardly extended flanges 1189 and 1190, and the inwardly extended relatively parallel flanges 1191 and 1192. The flange 1189 is engaged with the brackets 1179 by the screws 1193 and the flange 1190 is secured to the brackets 1173 by the screws 1195, so that, as will be observed, the reflector comprising the complementary concave sections, forming a reflector structure having a substantially parabolic contour, is supported by said brackets 1173 and 1179.

As best shown in Fig. 45, the flanges 1191 and 1192 of the reflector sections are secured to the bar 1196 of insulation material, preferably "Bakelite," by the screws 1197 to which bar the lamp supporting spring clip terminals 1198 and 1199 are attached by the screws 1200 and 1201 which extend through suitably provided apertures in said bar 1196 in threaded engagement with the terminal plates 1202 and 1203 respectively.

The spring clip terminals 1198 and 1199 are conveniently spaced to receive the terminal collars 1205 and 1206 of the tube type electric lamp 1207 which is provided with a backing of refractory material and which is supported by said spring clip terminals 1198 and 1199 in such predetermined relation to the parabolic reflector surface as to direct relatively parallel light rays through the glass pane 1172.

The terminal plates 1202 and 1203 are provided with the screw terminals 1209 and 1210, the terminal 1209 being connected by the electric wire 1212 with the terminal 1213 on the terminal plate 084 in the base of the spray bottle warmer, and the terminal 1210 being connected by the electric wire 1215 with the terminal 1216 on the terminal plate 085 in the base of said spray bottle warmer. However, the wire 1215 is connected through the rheostat switch 1217 which is arranged to be actuated by the controlling knob 1219.

As shown in Fig. 52, the wires 080 and 081 are included in the electric cord 1220 which enters the spray bottle warmer supporting arm 036 through the tubular elbow fitting guide 1222, and curves forwardly toward the free end of said arm into a free return loop 1223 from which it extends rearwardly into the loop 1225 permanently restricted by the clamp band 1226, and from which loop 1225 said cord 1220 extends forward through the supporting and directing clip 1227 from where it extends in the loop 1229 upwardly through the bushing 1230 in the free circular end 1231 of the bushing supporting bracket 1232 into the base 056 of the spray bottle warmer where said wires 080 and 081 are attached to their respective terminals, see Fig. 49.

Referring again to Fig. 52, the electric cord 1220 rests upon the floor 1233 which has that portion which is disposed between the elbow fitting guide 1222 and the loop 1223 backed by the guide 1235 formed of a strip of sheet spring material that is secured in any manner, such as by the rivets 1236, to the elbow fitting guides 1222 and extends curvedly forwardly therefrom, forming a backing for said electric cord 1220 and tending to prevent buckling thereof, and terminating in a preferably circular loop 1237 arranged to slide upon the inner surface of the rear wall 1239 of the spray bottle warmer arm 036.

With further reference to Fig. 52, it has been found desirable when the free end of the spray bottle warmer arm 036 is moved forwardly from its normal position with respect to the accessory table arm 170 and the electric cord 1220 has been

relatively shifted to the position shown in dot-and-dash lines in said figure, that the spring backing guide 1235 be maintained flattened in its medial region, and for this reason the inwardly curved region of the rear wall 1239 is provided with the elongated inwardly projecting abutment 1240 against which said backing guide may rest, as illustrated.

As shown in Fig. 53, the depending portion 1242 of the elbow 1222 extends into the sleeve 1243 which is supported by the flange 1245 resting upon the ledge 1246, and said sleeve 1243 is restricted at its lower end to provide a bearing 1247 for said elbow 1222, and said restricted end portion is provided with screw threads 1249 with which the nut 1250 is threadedly engaged.

As illustrated in Fig. 55, the bracket 1232, which is shown in perspective therein, has its inner end portion 1252 slightly depressed and terminates in the enlarged circular attachment 1253 having the aperture 1255 through which the screw 1256 extends, see Fig. 52, to engage it with the lug 1257 extending inwardly from the forward wall 1260 of the spray bottle warmer supporting arm 036. Said screw 1256 also engages the clip 1227 which, as shown in Fig. 56, has the circular attachment 1262 provided with the aperture 1263 through which said screw extends to attach it in superposed relation to the attachment 1253 of the bracket 1232.

Referring to Fig. 52, it will be obvious that the spring backing strip 1235 tends to maintain the electric cord 1220 in such curved relation, irrespective of the position of the spray bottle warmer arm with respect to the accessory table supporting arm upon which it is arranged to revolve, and that when said electric cord 1220 moves from its retracted position, shown in dot-and-dash lines, to its extended position, shown in full lines, it will be so reinforced and supported as to prevent its buckling or fouling, or otherwise tending to jam and interfere with the free movement of said spray bottle warmer arm.

The accessory table 632, upon which the table tray 633 is mounted, as shown in the several figures, particularly Figs. 2 and 42, may be eliminated and replaced by the adapter ring 1265 serving to space the tray 1267 at the proper distance above the table arm 170, as shown in Fig. 38. Said tray 1267 loosely rests upon the sheet metal tray rest 1269 which is secured by screws 1270 to the tray supporting frame 1272 mounted upon the adapter ring 1265 for relative rotation thereon, and being retained by the annular retainer 1273.

Said adapter ring 1265 is provided with the aperture 1275 through which the nipple 1276 of the air connector fitting 1277 extends, said fitting being rigidly engaged with said ring by the nut 1279 and its nipple 1276 being extended into the chamber 1280 for convenient connection with an air pipe or tube, not shown, but which corresponds to the air line pipe 762 shown in Fig. 16 as entering the annular mounting 173 for connection into the accessory table.

The air connector fitting 1277 has the flexible tube 1282 connected therewith by the screw threaded coupling 1283, which flexible tube 1282 connects said fitting with any desired air dispensing device, such as an air syringe, which may be conveniently supported when not in use or may be moved to any desired position limited only by the length of said tube 1282.

As shown in Fig. 57, the spot light 1285 comprising the electric lamp 1286 and reflector 1287

is mounted on the articulated arm 1290 comprising the relatively jointed arm sections 1291, 1292, and 1293, the arm sections 1291 and 1292 being connected for relative movement by the swivel joint coupling 1295, and the arm sections 1292 and 1293 being connected for relative movement by the swivel joint coupling 1296.

The inner end of the arm section 1293 is attached to the hollow projection 1297 extending radially from the sleeve 1299 which rotatably supports said spot light 1285 and its supporting articulated arm 1290, and which may be substituted for the spacer sleeve 74 shown in Fig. 9. Said sleeve 1299 is similar to said sleeve 74 in all respects except that it is provided with said hollow projection 1297 through which and the spot lamp supporting arm 1290 the electric cord 1300 extends to the lamp 1286 from a connection within the pedestal with a suitable source of current supply.

The wiring diagram shown in Fig. 58 particularly illustrates the connections between the instrument transformer 631 including the terminal bars 835 and 836 mounted on the water niche and cuspidor mounting section 3; the voltage control switch 1302 located in the accessory table 632 and controlled by the knob 624, shown in dotted line in Fig. 2; the booster transformer 905 located in the accessory table arm 170; the selector switch 890 having the switch control handle 900 projecting from the forward wall of said accessory table arm 170; the call button switch 941 having the push button 942 in said forward wall; and the instrument handle 1303 normally disposed in the accessory table and arranged to selectively removably and replaceably carry a cautery, pulp tester, mouth lamp, or other instrument, as may be desired.

As shown in said wiring diagram, Fig. 58, the line wires 1305 and 1306 are connected to the terminals 840 and 850 on the terminal bars, shown in Fig. 4, carrying the terminals connected to the several turns of the secondary coils 826 and 827, shown in Fig. 4.

The terminals of the instrument transformer 631 that are connected with the several turns of said secondary coils and on which terminals the voltage is indicated from two to six volts in one-half volt steps are connected by wires leading through the eleven-conductor-pin plug comprising the plug and socket members 917 and 918 respectively, to the corresponding volt indicated terminals on the voltage control switch 1302.

As shown in said wiring diagram in Fig. 58, the selector switch has the three contact terminals designated as 1-1, 3-1, and 10-1. When the contact arm 898 is in the position shown in dotted lines, engaged with the contact designated as 1-1 the voltage supplied to the instrument handle 1303 may be any voltage from two to six volts in one-half volt steps, depending upon the position of the contact arm 1315 of said voltage control switch 1302 which controls the varied voltage originating in the secondary coil of the instrument transformer, and in which dotted position of the contact arm 898 the booster transformer serves no purpose in volt modification.

If, however, the contact arm 898 be shifted to full line position to engage the contact designated 3-1, the voltage supplied to the instrument handle 1303 may be any voltage in one-and-one-half steps from six to eighteen depending upon the position of the contact arm 1315; for instance, if it be on the contact designating six volts, then the voltage delivered to the instrument handle

1303 will be eighteen volts, but if said contact arm 1315 be shifted to engage the contact designating four and one-half volts, then the voltage delivered to the instrument handle 1303 will be thirteen and one-half volts.

Should it be desired to further increase the voltage in the handle 1303, the contact arm 898 of the selector switch may be shifted to the position indicated by dot-and-dash lines to engage the contact designated as 10-1 in which instance the voltage supplied the instrument handle 1303 may be of any voltage in five volt steps from twenty to sixty depending upon the position of the contact arm 1315; for instance, if it be on the contact designating two volts, then the voltage delivered to the instrument handle 1303 will be twenty volts, and if said contact arm be on the contact designating four volts, the voltage delivered to said instrument handle will be forty volts, and if said arm be on the six volt contact, the voltage delivered to said instrument handle will be sixty volts.

It will be noted that the secondary coil of the booster transformer is electrically connected in parallel with the instrument handle, and is so designed that it has high impedance in this secondary circuit so that the wattage loss through said secondary coil is comparatively small, the impedance measured at six volts being found to be approximately fifteen thousand and nine hundred ohms.

It may be here noted that the booster transformer as designed cannot deliver from the secondary coil sufficient energy to detrimentally affect instruments that may be employed in the instrument handle 1303, such as a cautery, pulp tester, wax working instruments, mouth lamp, et cetera, even though the contact arm 1315 be on the six volt contact, and the contact arm 898 be on the contact designated 10-1 wherein the maximum of sixty volts would be delivered to the instrument handle. The limiting of energy is accomplished primarily by the employment of the limited amount of iron in the magnetic circuit and by use of fine wire giving high resistance for the booster transformer winding.

The combination of the booster transformer 905 and the instrument transformer 631, as herein described, is particularly advantageous in that there is afforded the ability to connect the instrument handle 1303 directly to the instrument transformer 631 which has a relatively large wattage rating from fifty to one hundred and fifty watts, and to the booster transformer 905 which receives its supply from the instrument transformer 631 and magnifies the voltage in the booster transformer three to one or ten to one, as the case may be, depending upon the position of the contact arm 898. These connections constitute such limited power that the cautery, wax instruments, mouth lamp, et cetera, will not be damaged for the reason that the voltage in the booster transformer is instantly pulled down when the secondary is connected across a relatively small resistance such as is obtained with a cautery, wax working instrument, or mouth lamp, each of which may be replaceably connected with the handle 1303.

My invention has many advantages over similar devices as heretofore constructed for supporting parts and accessories in convenient position for use by the professional operator, and affords not only easy access for use, but facilitates access for adjustment, repairs and replacement of all of said parts, and is particularly

adapted for eliminating parts that may not be desired by individual operators and the substitution or addition of parts and accessories that may be desired, by other operators, and, in this particular respect, it is possessed of individual flexibility and consequent superiority.

I do not desire to limit my invention to the precise details of construction and arrangement as herein set forth, as it is obvious that various modifications may be made therein without departing from the essential features of my invention as defined in the appended claims.

Having thus described my invention, I claim:

1. A dental equipment assemblage comprising a plurality of frame sections having flanges and being mounted one upon the other about a common axis, and a casing therefor formed of sections of sheet material having means arranged to engage said flanges for securing them together and also having means cooperative with said flanges for axially locating the casing section on the frame sections.

2. A dental equipment assemblage comprising a plurality of relatively separable frame members all being mounted on a common axis and having laterally extended flanges provided with indentations therein, a casing formed of a plurality of relatively separable sections formed of sheet material and having relatively inturned flanged portions engaging the indentations in said flanges by which they are held in place with respect to said frame members, said casing sections being capable of springing into place and being readily withdrawn therefrom.

3. A dental equipment assemblage comprising a plurality of frame sections mounted one upon the other about a common axis, means arranged to secure said sections together to form a rigid standard structure, the assembled frame providing suitably disposed guides, a supporting arm frame mounted to oscillate horizontally about said axis with respect to the frame sections thus assembled, bearing means arranged to rotatably support said frame with respect to said guides, a casing for said assembled frame sections comprising a plurality of casing sections engaged in rigid relation with said frame sections and forming a closure therefor, and a casing for said arm formed of a plurality of casing sections engaged with the arm frame and movable therewith relative to the stationary frame members and their casing sections.

4. A dental equipment assemblage comprising a plurality of frame sections mounted one upon the other in a predetermined sequence about a common axis, and having means whereby they may be readily secured together to afford a rigid supporting structure, the assembled frame structure providing suitably arranged tracks, a relatively movable supporting frame affording an extended arm mounted to be moved about said common axis, bearing rollers arranged to traverse said tracks and to carry the supporting arm frame, and removable and replaceable casing sections adapted to envelop the structure thus described.

5. A dental equipment assemblage comprising a plurality of frame sections mounted one upon the other in a predetermined sequence about a common axis, and having means whereby they may be readily secured together to afford a rigid supporting structure, the assembled frame structure providing suitably arranged tracks, a relatively movable supporting frame affording an extended arm mounted to be moved about said com-

70
75

mon axis, bearing rollers arranged to traverse said tracks and to carry the supporting arm frame, removable and replaceable casing sections adapted to envelop the structure thus described, and a bracket table mounted on the free end of said movable supporting frame.

6. A dental equipment assemblage comprising a plurality of frame sections mounted one upon the other in a predetermined sequence about a common axis, and having means whereby they may be readily secured together to afford a rigid supporting structure, the assembled frame structure providing suitably arranged tracks, a relatively movable supporting frame affording an extended arm mounted to be moved about said common axis, bearing rollers arranged to traverse said tracks and to carry the supporting arm frame, removable and replaceable casing sections adapted to envelop the structure thus described, a bracket table rotatably mounted on the free end of said movable supporting frame, and a secondary supporting arm movable horizontally about the axis of rotation of said bracket table.

7. A dental equipment assemblage comprising a plurality of frame sections built one upon the other about a common axis to provide a rigid supporting standard, a relatively movable supporting frame affording an extended arm having its inner end embracing said standard and arranged to be moved about said common axis, a bracket table mounted for independent rotation upon the free end of said movable supporting frame, a secondary supporting arm movable horizontally about the axis of said bracket table, a dental accessory device rotatably mounted on the free end of said secondary supporting arm, and removable and replaceable casing sections for said rigid supporting standard and said movable supporting frame, cooperative to provide an envelope for the structure thus described.

8. A dental equipment assemblage comprising a pedestal, a supporting arm carrying a cuspidor, a bracket table supporting arm, a dental engine arm carrying a handpiece all mounted to swing about the common axis of said pedestal, and an electric motor mounted in said pedestal and having its armature coincident with said axis and connected through the wall of said pedestal to drive said engine.

9. A dental equipment assemblage comprising an equipment supporting standard, a casing formed of a plurality of casing sections embracing said standard and cooperative to form a pedestal, a cuspidor carrying arm and a bracket table carrying arm mounted for independent horizontal adjustment to swing about the axis of said standard, an electric motor enclosed within said pedestal and having its armature shaft arranged to rotate on said axis and extended vertically through the wall of said pedestal, a dental engine arm swingably mounted at the top of said pedestal and connected with said motor shaft to drive a handpiece carried by said engine arm.

10. A dental equipment unit comprising a pedestal having a removable casing assembled about a unitary common axis, a motor mounted in said pedestal and having its driving shaft arranged to rotate on said axis, an extension for said shaft projected through the wall of said pedestal, an engine arm mounted to rotate about said axis and carrying a handpiece connected to be driven by the motor, said motor being mounted to swing horizontally out of alinement with said axis.

11. A dental equipment unit comprising a pedestal having a removable dome capped casing

including several separable sections assembled about a common axis, an electric motor mounted in said pedestal and having its armature shaft mounted to rotate on said axis and extended to project through the dome of said pedestal, an engine arm mounted to rotate about said axis and carrying a handpiece connected to be driven by the motor through said armature shaft, said electric motor being mounted to swing horizontally out of its normally operative alinement with said axis and means adjustable to hold said motor in axial alinement with the casing of said pedestal.

12. A dental equipment assemblage comprising a plurality of frame sections mounted one upon the other and forming a standard having an axis common to all of said frame sections, an electric motor suitably mounted in one of said frame sections with its armature coaxial with the axis of said standard, a casing for said standard enclosing said frame sections and formed of a plurality of removable and replaceable casing sections of sheet material enclosing said frame sections, a shaft for said armature extended through said casing and provided with belt driving pulleys, a rotatable collar mounted at the top of said standard arranged to rotate about the axis of said armature shaft and having a bearing thereon, and a dental engine arm supported in said bearing, a handpiece on said engine arm, and a belt connecting said handpiece with any selected one of the pulleys on said armature shaft.

13. A dental equipment assemblage comprising a supporting standard structure formed of a plurality of frame sections assembled about a unitary axis and having a circular trackway, an accessory supporting arm projecting radially from said structure and arranged to revolve about said axis, bearing rollers arranged to rotatably support said arm and thereby facilitate its free movement, an accessory table rotatably mounted on the free end of said arm and including a plurality of operative devices employed in the practice of dentistry, a fluid conveying tube extending upwardly through said standard structure and horizontally through said arm into said table, and having a flexible intermediate section spirally coiled about said axis and arranged to permit the free movement of said arm and table carried thereby.

14. A dental equipment assemblage comprising a supporting standard structure formed of a plurality of frame sections assembled about a unitary axis and having a circular trackway, an accessory supporting arm projecting radially from said structure and arranged to revolve about said axis, bearing rollers arranged to rotatably support said arm and thereby facilitate its free movement, an accessory table rotatably mounted on the free end of said arm and including a plurality of operative devices employed in the practice of dentistry, a fluid conveying tube extending upwardly through said standard structure and connected through a stationary coupling on said standard with a flexible section spirally coiled about said axis and leading into said arm and connected with a device for controlling the flow therethrough.

15. A dental equipment assemblage comprising a supporting standard structure formed of a plurality of frame sections assembled about a unitary axis and having a circular trackway, an accessory supporting arm projecting radially from said structure and arranged to revolve about said axis, bearing rollers arranged to rotatably support said arm and thereby facilitate its free movement, an accessory table rotatably mounted on

the free end of said arm and including a plurality of operative devices employed in the practice of dentistry, a fluid conveying tube connecting a source of supply with an operative appliance on said arm, and comprising a section extending upwardly through said standard structure, a section spirally coiled about the axis of said standard structure, and a section leading through said arm.

16. A dental equipment assemblage comprising a supporting standard structure formed of a plurality of frame sections assembled about a unitary axis and having a circular trackway, an accessory supporting arm projecting radially from said structure and arranged to revolve about said axis, bearing rollers arranged to rotatably support said arm and thereby facilitate its free movement, an accessory table rotatably mounted on the free end of said arm and including a plurality of operative devices employed in the practice of dentistry, a fluid conveying tube connecting a source of supply with an operative appliance on said arm, and comprising a section extending upwardly through said standard structure, and connected through a coupling on said standard structure with a section spirally coiled about the axis of said standard structure and connected through a coupling fixture with a section extending through said arm.

17. A dental equipment assemblage comprising a supporting standard formed of a structure having a unitary axis, an accessory supporting arm projecting radially from said structure and arranged to revolve about said axis, a bracket table structure rotatably mounted on said arm and including a fluid dispensing appliance, a fluid conveying tube connecting a source of supply with said operative appliance and comprising a section extending upward through said standard and connected through a coupling on said standard with a yielding section spirally coiled about said axis and connected through a coupling fixture on said arm with a section extending through said arm and table to said fluid dispensing appliance.

18. A dental equipment assemblage comprising a supporting standard formed of structure having a unitary axis, an accessory supporting arm projecting radially from said structure and arranged to revolve about said axis, an accessory assemblage mounted on said arm and rotatable with respect thereto and including a syringe, a fluid conveying tube connecting a source of fluid supply with said syringe, and including a portion extending upwardly through said standard, a yielding portion spirally coiled about said axis, and a portion extending through said arm and table.

19. A dental equipment assemblage comprising a supporting standard formed of a structure having a unitary axis, an accessory supporting arm projecting radially from said structure and arranged to revolve about said axis, an accessory assemblage mounted on said arm and rotatable with respect thereto, fluid conveying tubes each connecting a source of fluid supply with a fluid dispensing device and including a yielding portion spirally coiled in respectively opposite directions about said axis, a portion depending therefrom through said standard and connected with said source of fluid supply, and a portion extending through said arm to said fluid dispensing device.

20. A dental equipment assemblage comprising a supporting standard formed of a structure having a unitary axis and provided with an annular shelf, an accessory supporting arm projecting

radially from said structure and arranged to revolve about said axis, a fluid conveying tube leading upwardly through said standard and connected with a tubular coupling stationary on said standard, a flexible spirally coiled extension of said fluid conveying tube resting on said shelf and detachably connected with a hollow connection fixture carried by said arm, and a fluid conveying tube leading from said connection fixture through said arm to a suitable fluid dispensing device carried by said arm.

21. A dental equipment assemblage comprising a supporting standard formed of a structure having a unitary axis and provided with an annular shelf, an accessory supporting arm projecting radially from said structure and arranged to revolve about said axis, a fluid conveying tube leading upwardly through said standard and connected with a hollow coupling stationary on said standard, a flexible spirally coiled extension of said fluid conveying tube resting on said shelf and detachably connected with a hollow connection fixture carried by said arm and comprising a passageway leading therethrough encircled by an annular seat and having a slot opening laterally with respect to the axis of said seat, and a fluid conveying tube carried by said arm and having a terminal fitting arranged to be connected and disconnected by movement through said slot, and adjustably maintained in removable fluid tight relation to said seat.

22. A dental equipment assemblage comprising a supporting standard formed of a structure having a unitary axis and provided with an annular shelf, an accessory supporting arm projecting radially from said structure and arranged to revolve about said axis, a fluid conveying tube leading upwardly through said standard and connected with a tubular coupling stationary on said standard, a flexible spirally coiled extension of said fluid conveying tube resting on said shelf and detachably connected with a hollow connection fixture carried by said arm and comprising a passageway leading therethrough encircled by an annular seat and having an opening disposed lateral to the axis of said seat, a fluid conveying tube extending through said arm and having an inner substantially semi-spherical terminal fitting removably engaged with said seat through said opening, and a socketed screw-plug threadedly engaged in said fixture and adjustable to maintain said fitting engaged with said seat.

23. A dental equipment assemblage comprising a supporting standard structure formed of a plurality of frame sections assembled about a unitary axis and having a circular trackway, an accessory supporting arm projecting radially from said structure and arranged to revolve about said axis, bearing rollers arranged to rotatably support said arm and thereby facilitate its free movement, means tending to retard the movement of said arm, means arranged to lock said arm and thereby restrain its movement with respect to said standard structure, and means actuated by manual pressure tending to move said arm in either direction, arranged to effect release of said lock and permit it to revolve about said axis.

24. A dental equipment assemblage comprising a supporting standard structure formed of a plurality of frame sections assembled about a unitary axis and having a circular trackway, an accessory supporting arm projecting radially from said structure and arranged to revolve about said axis, bearing rollers arranged to rotatably support said arm and thereby facilitate its free movement,

means tending to retard the movement of said arm, means arranged to lock said arm and thereby restrain its movement with respect to said standard structure, and, means including push and pull mechanism, actuated by manual pressure tending to move said arm in either direction, arranged to effect release of said lock and permit it to revolve about said axis.

25. A dental equipment assemblage comprising a supporting standard having a lock engaging surface, an accessory supporting arm projecting radially from said standard and arranged to revolve horizontally thereabout, locking mechanism carried by said arm and comprising a body having relatively angular surfaces inclined with respect to said lock engaging surface but spaced therefrom, bearing balls disposed between the thus opposed surfaces and arranged to roll thereon, yielding means tending to force said balls into contact with said opposed surfaces, and means, actuated by manual pressure tending to move said arm, arranged to force said balls out of such contact and thereby prevent their jamming and consequent locking action.

26. A dental equipment assemblage comprising a supporting standard having a lock engaging surface, an accessory supporting arm projecting radially from said standard and arranged to revolve horizontally thereabout, locking mechanism carried by said arm and comprising a body having relatively angular surfaces inclined with respect to said lock engaging surface but spaced therefrom, bearing balls disposed between the thus opposed surfaces and arranged to roll thereon, yielding means tending to force said balls into contact with said opposed surfaces, and means, including a tapered plunger mounted to force said balls out of such contact and thereby prevent their jamming and consequent locking action, and mechanism linked with said plunger and including a push and pull device arranged to be manually employed to move said arm in either direction about said stand and thereby actuate said plunger to determine the position of said balls for locking or release of said arm.

27. A dental equipment assemblage comprising a supporting standard having a lock engaging surface, an accessory supporting arm projecting radially from said standard and arranged to revolve horizontally thereabout, locking mechanism carried by said arm and comprising a body having relatively angular surfaces inclined with respect to said lock engaging surface but spaced therefrom, bearing balls disposed between the thus opposed surfaces and arranged to roll thereon, yielding means tending to force said balls into contact with said opposed surfaces, and means, including a tapered plunger mounted to force said balls out of such contact and thereby prevent their jamming and consequent locking action, yielding means tending to normally withdraw said plunger from active contact with said balls, a bell-crank-lever cooperatively associated to effect movement of said plunger into operative position to render said balls inoperative, a link extending through said arm and terminating in the free end portion thereof, a push and pull rod extending transversely through said free end portion and projecting outwardly from the forward wall thereof and provided with a handle, and a bell-crank-lever connecting said link and rod whereby the unlocking action of said balls may be effected either by manually pushing or pulling on said handle.

28. A dental equipment assemblage comprising

a supporting standard formed of separable sections disposed one upon another, an annular disk engaged between adjacent sections and affording a lock engaging surface, an accessory supporting arm projecting radially from said standard and mounted to freely revolve horizontally thereabout, locking mechanism carried by said arm and comprising a block having relatively angular faces inclined with respect to said lock engaging surface and spaced with respect thereto, rotatable bearing members disposed between the opposed relatively angular faces of said block and disk and arranged to roll thereon, means tending to cause said rotatable members to normally contact with said opposed faces to effect jamming and consequent locking of said arm with said standard and in rigid relation, and push and pull mechanism actuated by manual effort in moving said arm in either direction about said standard, arranged to effect release of said rotatable members from jamming contact and permit free movement of said arm.

29. A dental equipment assemblage comprising a supporting standard formed of separable sections disposed one upon another, an annular disk engaged between adjacent sections and affording a lock engaging surface, an accessory supporting arm projecting radially from said standard and mounted to freely revolve horizontally thereabout, locking mechanism carried by said arm and comprising a block having relatively angular faces inclined with respect to said lock engaging surface and spaced with respect thereto, rotatable bearing members disposed between the opposed relatively angular faces of said block and disk and arranged to roll thereon, means tending to cause said rotatable members to normally contact with said faces to effect jamming and consequent locking of said arm with said standard in rigid relation, friction means carried by said arm, engaging said disk, and serving as a brake cooperating with said locking mechanism when released to restrict the free movement of said arm and prevent its over running movement, and mechanism actuated by manually moving said arm in either direction about said standard, arranged to effect release of said locking mechanism during such movement of said arm.

30. A dental equipment assemblage comprising a supporting standard structure formed of a plurality of separable frame sections disposed one upon another about a unitary axis, a motor supported in said standard and having its driving shaft disposed coaxial with the axis of said standard, a dental engine mounted on said standard and having its arm arranged to swing about said axis, a handpiece carried at the free end of said engine arm, means connecting said handpiece with said driving shaft, and a cradle hingedly supported on said standard and arranged to carry said motor into and out of coaxial alignment with said standard.

31. A dental equipment assemblage comprising a supporting standard structure formed of a plurality of separable frame sections disposed one upon another about a unitary axis, a motor supported in said standard and having its driving shaft disposed coaxial with the axis of said standard, a dental engine mounted on said standard and having its arm arranged to swing about said axis, a handpiece carried at the free end of said engine arm, and means connecting said handpiece with said driving shaft, a cradle hingedly supported on said standard and arranged to carry said motor into and out of coaxial alignment

with said standard, and means adjustable to secure said cradle in position to retain said motor in coaxial alinement with said standard.

32. A dental equipment assemblage comprising a supporting standard structure formed of a plurality of separable frame sections disposed one upon another about a unitary axis, a motor supported in said standard and having its driving shaft disposed coaxial with the axis of said standard, a dental engine mounted on said standard and having its arm arranged to swing about said axis, a handpiece carried at the free end of said driving shaft, a cradle hingedly supported on said standard and arranged to carry said motor into and out of coaxial alinement with said standard, means arranged to limit the movement of said cradle, and an adjusting screw arranged to hold said cradle in operative relation to said movement limiting means.

33. A dental equipment assemblage comprising a plurality of frame sections having a unitary axis, a cradle hingedly supported in the uppermost one of said sections and arranged to swing free thereof, resilient supports on said cradle, a motor carried by said cradle and resting on said resilient supports with the axis of its shaft disposed coaxially with said unitary axis, an extension shaft rotatably journaled to rotate on said axis, a flexible coupling arranged to detachably connect said extension shaft with the motor shaft, and means exterior to said frame sections, connected to be actuated by said motor shaft through the medium of said extension shaft.

34. A dental equipment assemblage comprising a plurality of frame sections, including a dome section, and built one upon another about a unitary axis to provide a supporting standard structure, a bearing mounting structure detachably seated on said dome section in coaxial relation with said frame sections, a cradle hingedly mounted to swing into and out of said dome section, a stop for said cradle arranged to determine its position within said section, means adjustable to rigidly engage said cradle with said stop, resilient supports carried by said cradle, an electric motor floatingly mounted on said resilient supports with its shaft normally coaxial with said dome section, a shaft extension rotatably mounted in said mounting structure and projecting upwardly exterior to said dome section, a resilient coupling adjustable axially between the adjacent ends of said shaft and said shaft extension to connect them to rotate together, and means rotatably supported on said bearing mounting section and connected to be actuated by said motor through said shaft and its extension.

35. A dental equipment assemblage comprising a plurality of frame sections, including a dome section, and built one upon another about a unitary axis to provide a supporting standard structure, a bearing mounting structure detachably seated on said dome section in coaxial relation with said frame sections, a cradle hingedly mounted to swing into and out of said dome section, a stop for said cradle arranged to determine its position within said section, means adjustable to rigidly engage said cradle with said stop, resilient supports carried by said cradle, an electric motor floatingly mounted on said resilient supports with its shaft normally coaxial with said dome section, and including a shaft extension detachably connected therewith and projecting upwardly beyond said dome section, a dental engine, arranged to carry a hand-

piece, having its base mounted on said mounting section and arranged to rotate about said axis, pulleys on said shaft extension on said engine and said handpiece, belting connecting said shaft and handpiece by means of said pulleys, a spot light support having its base mounted on said dome section and arranged to rotate about said axis, and an electric lamp connected through said support and standard structure with a source of electric current supply.

36. A dental equipment assemblage comprising a plurality of frame sections and including a dome section disposed in superposed relation about a common axis, a bearing mounting detachably seated on said dome section in coaxial relation therewith, a dental engine including a handpiece having its base mounted to rotate on said mounting about said axis, a spot light support including an articulated arm having its base mounted to rotate on said mounting about said axis, a lamp connected through said arm, its mounting, and said standard structure, with a suitable source of electric current supply, a motor in said dome section having a shaft coaxial with said mounting and extended therethrough, and means connecting said shaft with said handpiece to effect its actuation.

37. A dental equipment assemblage comprising a supporting standard formed of a plurality of variably shaped separable frame sections including a dome section superposed one upon another about a unitary axis, a control panel mounted on said dome section and supporting controlling devices, including valves and electric switches through which the air, gas and electric current pass to the various devices employed, the air pressure controlling device being arranged to control the passage of air through its conveyor including a pressure regulator and a filter, each being detachably supported on said panel and also removable from said dome section with said panel as a unit.

38. A dental equipment assemblage comprising a supporting standard formed of a plurality of variably shaped separable frame sections including a dome section superposed one upon another about a unitary axis, a control panel mounted on said dome section and supporting controlling devices, including valves and electric switches through which the air, gas and electric current pass to the various devices employed, the air pressure controlling device being arranged to control the passage of air through its conveyor including a pressure regulator and a filter, each being detachably supported on said panel and also removable from said dome section with said panel as a unit, and a removable and replaceable casing for said standard, including apertures arranged to register with said valves and switches et cetera and through which they may be manually operated.

39. A dental equipment stand comprising a standard having a casing formed of relatively separable flexible casing sections having their free edges flanged and the flanged edges of one abutted with the free flanged edges of another, and a yielding strap girdling said casing sections and normally holding them together but having means including an elongated slot arranged to permit the elongation of said strap, and means cooperative with said slot arranged to permit the relative limited separation of said casing section.

40. A dental equipment stand comprising a standard frame having a plurality of peripheral

flanges provided with notches in the peripheral edges thereof, a housing for said standard frame formed of relatively separable housing sections having lateral inturned flanges arranged to be engaged in said notches in relatively abutted relation with cooperative sections, and having inset end margins forming shoulders cooperative with the frame flanges to axially locate said housing sections with respect to said standard frame.

41. A dental equipment stand comprising a standard frame having relatively spaced peripheral flanges, a housing for said standard frame formed of relatively separable housing sections having their end margins formed to provide shoulders arranged to engage said flanges and thereby determine the axial position of said housing sections with respect to the standard frame.

42. A dental equipment supporting frame comprising a composite column formed about a unitary axis, an accessory support arranged to rotate about said frame and a fluid conveying

conductor extending through said frame and connecting a source of fluid supply with an accessory device on said support and including a yielding portion looped within said column, and 5 permitting free rotation of said accessory support about said axis.

43. A dental equipment stand casing comprising a plurality of relatively separable flexible casing sections formed of sheet material independently movable in rectilinear paths, and having their free lateral edges abutted with respect to the free lateral edges of adjacent casing sections, and yielding means tending to maintain them in relatively abutted relation.

44. A dental equipment stand casing comprising relatively separable flexible casing sections yieldingly joined to form a pedestal envelope and independently movable in rectilinear paths, and a yielding strap girdling said sections and 10 normally holding them together but capable of limited elongation to permit said sections to separate under internal pressure.

ROBERT C. ANGELL.
